UNITED STATES PATENT OFFICE

2,692,463

MACHINE FOR CLOSING CARTONS

Isaac L. Wilcox, Fulton, and Alfred A. Barnes,
 Clarence E. Patch, and Robert Spurr, Syracuse,
 N. Y., assignors to Oswego Falls Corporation,
 Fulton, N. Y., a corporation of New York

Application May 8, 1948, Serial No. 25,944

25 Claims. (Cl. 53—44)

1

This invention has to do with a machine structure for automatically applying and sealing end closures to an advancing procession of open ended cartons. More particularly, the invention relates to a machine for forming end closures from flat blanks, applying and sealing the same to the open ended cartons, the cartons being formed of sheet fibrous material, such as paperboard. An example of such a carton is disclosed in the co-pending application of Isaac L. Wilcox, Ser. No. 552,940, now U. S. Patent No. 2,470,984. The cartons of the type referred to are particularly well suited for packaging liquid and semi-liquid food products, such as various grades of milk, cream, and other dairy products.

The machine herein disclosed constitutes a part of an apparatus adapted to be operated in a dairy or packaging plant for automatically making cartons from flat blanks, filling the cartons, forming end closures from flat blanks, applying the end closures to the open ends of the filled cartons, and sealing the closures to the cartons. The mechanism for filling the cartons is incorporated in the structure herein disclosed. However, the filling mechanism per se does not form part of this invention.

The invention has as a general object mechanism operable to intermittently advance a procession of cartons, preserving a portion of the top edge of each carton advanced in the procession with a non-sealable material forming a seal baffle or block to prevent a portion of the top end closure from permanently sealing to the carton, forming end closures from flat blanks, applying and sealing the same to the tops of the cartons, the mechanisms for performing these various functions embodying a particularly reliable and durable structure, rendering the machine particularly efficient in dairy operation.

The invention has as a further object a carton advancing means movable intermittently over a carton guide rail, forwardly to advance a procession of cartons along the rail, and then outwardly in spaced relation to the rail, the mechanism embodying a structure by which the cartons are intermittently moved at high speed without agitating the contents of the filled cartons.

The invention has as a further object mechanism operable to apply non-sealable material to a corner portion of each top edge of the carton, the mechanism embodying a structure which is capable of being operated at high speed.

The invention has as a further object a machine of the type referred to embodying a structure operable automatically to successively with-

2

draw flat blanks from a supply, sterilize the same, form the sterilized blanks into end closures, and apply the same successively to the advancing cartons of a procession.

5 The invention has as a further object novel mechanism for rendering the seal baffle applying mechanism and the top closure applying mechanism inoperable in the event a carton is absent, or missing, in the procession of cartons being advanced.

The invention consists in the novel features and in the combinations and constructions hereinafter set forth and claimed.

In describing this invention, reference is had 15 to the accompanying drawings in which like characters designate corresponding parts in all the views.

Figure 1 is a side elevational view of the machine embodying our invention.

20 Figure 2 is an end elevational view looking to the right, Figure 1, with parts broken away and parts in section.

Figure 3 is a top plan view of the machine shown in Figure 1, with the structures above the 25 carton conveyor removed, on a line corresponding to line 3—3, Figure 2.

Figure 4 is a vertical sectional view of the structure shown in Figure 3 taken on line 4—4, Figure 2.

30 Figure 5 is a transverse sectional view of the cam housing taken on line 5—5, Figure 2.

Figure 6 is a sectional view of the conveyor rail supporting mechanism, cam housing, and contiguous portion of the base taken on line 35 6—6, Figure 3, the carton advancing mechanism being omitted.

Figure 7 is a front elevational view of the conveyor elevating mechanism.

Figure 8 is a top plan view of the structure 40 shown in Figure 7.

Figure 9 is a rear elevational view of the structure shown in Figure 8 with the cover plate broken away.

Figure 10 is an enlarged sectional view on line 45 10—10, Figure 7.

Figure 11 is an enlarged sectional view on line 11—11, Figure 7.

Figure 12 is a sectional view taken on a line corresponding to line 12—12, Figure 11.

50 Figure 13 is a sectional view taken on a line corresponding to line 13—13, Figure 11.

Figure 14 is a view of the cam member shown in Figures 10 and 11.

55 Figure 15 is a top plan view of the pawl shown in Figure 12.

3

Figure 16 is an enlarged fragmentary sectional view showing the arrangement of the interlock switch actuating mechanism.

Figure 17 is a fragmentary view of the interlock mechanism taken on a line corresponding to line 17-17, Figure 10.

Figure 18 is a view taken on line 18-18, Figure 4, showing a portion of the conveyor elevating mechanism in elevation.

Figure 19 is a fragmentary sectional view through a portion of the housing showing the arrangement of the transverse shaft of the conveyor elevating mechanism, the view being taken at the location indicated by line 19-19, Figure 18.

Figure 20 is a front elevational view of the carton advancing mechanism and supporting columns therefor, with parts broken away, and parts in section.

Figure 21 is a sectional view taken on line 21-21, Figure 3.

Figure 22 is a sectional view taken on line 22-22, Figure 21.

Figure 23 is a sectional view taken on line 23-23, Figure 3.

Figure 24 is a sectional view taken on line 24-24, Figure 3.

Figure 25 is a top plan view of the strip applying mechanism shown at the upper left Figure 1.

Figure 26 is a side elevational view of the strip applying mechanism.

Figure 27 is a view taken on line 27-27, Figure 25.

Figure 135 is a top plan view of a sealing head frame carrying bracket.

Figure 136 is a schematic wiring diagram of the conveyor interlock elevating mechanism.

Figures 137, 138, 139, 140 and 141 illustrate diagrammatically the succession of operations performed on the carton by the machine herein disclosed.

The machine consists generally of an elongated base, on the top of which there is mounted a cam housing extending lengthwise thereof. Conveyor mechanism is arranged on the top of the cam housing and is operable to intermittently advance two processions of open ended cartons, the cartons being advanced from the left end of the machine, Figure 1, to the right end.

There are a plurality of carton processing mechanisms arranged above the conveyor mechanism. At the left end of the machine, a corner portion of the top edge of each carton is preserved with a non-sealable material. Thereafter, the cartons are filled by filling mechanism arranged above the conveyor. During the advancement of the open ended cartons, end closure blanks are successively withdrawn from a supply, conditioned for application, formed into end closures, and applied to the open ends of the then filled cartons. At the right hand end of the machine, sealing mechanism is arranged and functions to securely seal the applied closures to each carton top. In explaining the general operation of the machine, reference is first made to Figures 137—141 inclusive, which illustrate diagrammatically the successive operations performed on the cartons during the advancement by the conveyor mechanism. The carton in Figure 137 is illustrated as being positioned at the left hand end of the machine, Figures 1 and 3, on an elevating pedestal 248. At this position, a strip of non-sealable material, such as metallic foil, is fed downwardly to arrange the leading end of the strip in juxtaposition to one corner portion of the top of the carton. This leading portion 257 of the strip is severed and is folded over the top edge of the carton at the corner portion thereof and downwardly on the interior of the carton, as indicated at 426, Figure 138.

The cartons, with the non-sealable material so positioned on the top corner edge portion thereof, are lowered by the pedestal and are advanced by a carton conveyor mechanism to and past the filling mechanism 540. While being so advanced, a procession of top closure 75

blanks 614 are advanced through conditioning means, and as the cartons reach the pedestals 523, Figure 3, these conditioned blanks 614 are formed into top closures and inserted into the tops of the cartons.

In this forming operation, the peripheral portions of the blanks 614 are formed into an inverted channel having inner walls 900 and outer walls 901, as illustrated in Figure 140. The cartons, with the top closures so applied thereto, are then advanced to pedestals 512, 522, by which they are elevated into operative position to top closure sealing mechanisms which are operable to seal the inverted channel of the top closure to the top edge of the carton, as illustrated in Figure 141.

The base 20 is supported by a plurality of leveling pads 21 positioned on the floor. The cam housing 22 is detachably secured to the top of the base by a number of screws 23. A main cam shaft 24 extends lengthwise of the cam housing and is journaled in bearings 25. The shaft 24 extends through the left hand end of the housing and is provided with a gear 26 meshing with a gear 27 continuously rotated as by a motor 28 through a chain or belt 29, see Figure 2. The gears 26, 27, are enclosed in a suitable housing 30.

The cartons are intermittently advanced in a procession along guide rails 32. These guide rails extend along opposite sides of the cam housing 22 and are supported by screws 33 which are operable to adjust the rails vertically toward and from the top of the housing 22. Each rail is supported by two of the screws 33 located adjacent each end of the housing, see Figure 5. The guide rails are affixed to inverted channel structures 36 which, in turn, are mounted upon head members 37, as by screws 38. These head members are apertured to receive reduced end portions 39 of the screws, the head members being split and fixedly clamped to the screws 33, as by bolts 40, see Figure 6.

The screws 33 are slidably mounted for vertical movement in sleeves 41 mounted in the housing 22, the sleeves being provided with antifriction bushings 42 at the upper and lower ends. The housing 22 is formed with recesses 43 for the exposed portion of the sleeves 41, see Figures 5 and 6. The elevating screws are provided with sleeves 44 depending from the head members 37 and telescoping over the upper portions of the sleeves 41. The conveyor rails 32 are shown in the lowermost position, Figure 6. When these rails are elevated by the screws 33, the outer sleeves 44 serve to protect the upper portion of the elevating screws extending beyond the upper ends of the sleeves 41 from moisture, dirt, etc. The sleeves 41 are fixedly secured in the cam housing by clamp nuts 47 threaded on the lower ends of the sleeves.

The lower ends of the screws 33 are threaded to receive nuts 48 journaled in supporting brackets 49 mounted in the base. A gear 50 is secured to each of the nuts 48, see Figures 6 and 18, and these gears are arranged in mesh with gears 51 journaled on studs 52 also mounted in the brackets 49. The gears 51 are arranged in mesh with gears 53 mounted on a shaft 54 journaled in the base and extending lengthwise thereof, see Figures 4 and 18. There is a gear 53 secured to each end of the shaft 54, the gear meshing with pairs of the gears 51 whereby, upon rotation of the shaft 54, all four of the nuts 48 are rotated simultaneously to effect elevation of the screws 33 and the guide rails 32 carried thereby.

The shaft 54 is rotated by a crank 56 carried on a shaft 57 journalled in a housing 58 mounted externally of the cam housing 22 on the forward side of the base 20. A gear 60 is keyed to the shaft 57 and is arranged in mesh with a gear 61 journalled on a stud 62 in the housing 58. The gear 61 depends through an opening in the top wall of the base 20 and meshes with a gear 64 keyed to a shaft 65 journalled in the base and extending transversely thereof. The inner end of the shaft 65 is provided with a gear 66 arranged in mesh with a gear 67 keyed to the shaft 54. Accordingly, when the shaft 57 is rotated by the crank 56, all four of the nuts 48 are rotated effecting vertical movement of the screws 33. The purpose of this adjustment, as will be apparent later on in the description, is to accommodate the machine for handling cartons of different heights and capacities, such as quarts, pints, and half pints.

It is desirable that this adjustment of the carton conveyor guide rails be made conveniently and with relatively great accuracy. This accurate adjustment is obtained by mechanism arranged in the housing 58. Referring to Figure 11, a disk 70 is arranged on the inner surface of the front wall of the housing. This disk is formed, at its periphery, with two diametrically arranged slots 71 engaging the heads of two pins 72 carried by the front wall of the housing. The disk is provided with a central enlarged aperture 73 to clear the shaft 57 and parts carried thereby. With this arrangement, the disk is free to move vertically.

An eccentric 74 is fixed to the shaft, and a disk 75 is mounted upon the eccentric. The disk 75 is held against rotation by pins 76 carried thereby and extending into another pair of diametrically opposed slots 77 formed in the disk 70, these slots 77 being spaced 90° from the slots 71, see Figures 7 and 10.

The disk 75 is provided with a plurality of pins 78 extending inwardly within an annular flange 79 formed on a disk 80. The inner surface of the flange 79 is formed with a plurality of concavities 81.

With this arrangement, upon rotation of the shaft 57, an eccentric motion is imparted to the disk 75 causing the pins 78 to successively engage with the concavities 81. The number of concavities greatly exceeds the number of pins, and with a ratio of seven pins and fifty concavities, effects one-fiftieth rotation of the disk 80 upon one rotation of the shaft 57. In other words, this arrangement effects, in a minimum space, a reduction of great magnitude.

A disk 82 is keyed to the shaft 57. The periphery of this disk is provided with a cam lobe 83, 180° in extent. The periphery of the disk 80 is formed with notches 84, 85, 86, these notches corresponding to adjustments of the carton guide rails 32 for quart, pint and half-pint cartons, respectively. The periphery of the disk 80 is also provided with indicia of "Quart, Pint and Half Pint," these indicia being visible through a transparent window 89 arranged in the top of the housing 58. The periphery of the cam disk 82 is provided with an indicia "Run" also visible through the window 89.

A pawl 90 is journalled in the housing 58 on the pin 62. The pawl is provided with a narrow tail portion 92, see Figure 15, positioned to be engaged by a cam section 94 carried on the face of the disk 80 and on the periphery of the flange 79, see Figure 13. At its opposite end, the pawl 90 is formed with a wide nose piece 95 arranged

in alinement with the periphery of the disk 82, and also the periphery of the disk 80.

The pawl 90 is also formed with a lower tail portion 96 positioned to be engaged by a cam 5 97 secured to a shaft 98. One end of the shaft 98 extends through the front wall of the housing and has attached to it an operating knob 99. The opposite end of the shaft extends into a compartment 100 provided with a closure plate 101. A bracket 102 is mounted in this compartment, as by screws 103. The lower portion of the bracket is bored to receive a short shaft 104 having an enlarged head 105 formed with a slot 106 to receive a projection on the end of 15 the shaft 98, see Figures 10 and 17, whereby, upon rotation of the shaft 98 by the knob 99, the stub shaft 104 is rotated.

The enlarged head 105 is milled off from a point 108, Figure 17, clockwise to the pin 109 20 projecting from the bracket 102 to permit the shaft 104 to be rotated 180°. The stub shaft 104 is formed with a depression in which is normally positioned the head 110 of a pin 111, the head being yieldingly urged into the recess by 25 a helical compression spring 112 mounted in a boss 113 constituting a part of the bracket 102.

The stub shaft 104 is also formed with a recess 30 to receive a pin 114 connected to the armature of a solenoid 115. The pin 114 is urged into its recess by a helical compression spring 116. When the pin 114 is in engagement with its recess, the shaft 98 can not be rotated by the knob 99. One side of the solenoid 115 is connected to the hot side 117 of a source of current. The opposite 35 side of the solenoid is connected to the common side 118 of the source through contacts 119, wire 120, switch 121, wire 122, see Figure 136. The contacts 119 are associated with the starter for the driving motor 28, the contacts 119 being closed when the contacts of the motor starter 40 are open. The switch 121 is operated by the carton advancing mechanism. As will be more fully explained hereinafter, this mechanism consists of a rake-like member operated through repeated cycles of rectangular movement wherein the carton advancing member moves inwardly over the 45 guide rails 32 forwardly, outwardly clear of the guide rails, and rearwardly to the starting position. It will be apparent that it is necessary to have this advancing member positioned outwardly clear of the guide rails 32 before the rails 50 can be elevated. The arrangement is such that the normally open contacts of the switch 121 are closed when the carton advancing member is in the outward position.

When the machine is stopped by opening the main contacts of the motor starter and closing the contacts 119, and the carton advancing mechanism is in its outward position with the contacts of switch 121 also closed, a circuit is completed through the solenoid 115, as explained above, and accordingly the operator can turn shaft 98 by the knob 99, moving the pin 111 outwardly against the spring 112. Such outward movement of the pin engages the actuating mechanism of a switch 123. The contacts of the switch 123 are normally closed, furnishing current to the hot side 117 of the line. When the switch is actuated by the pin 111, the contacts 60 thereof are open, thus opening the control circuit shown in the diagram Figure 136 and with this circuit open, the motor starter can not be actuated or, in other words, the machine can 65 not be operated.

It is necessary for the operator to so rotate

the shaft 98 before making any vertical adjustment of the guide rails because when the machine is in operating condition the nose piece 95 of the pawl 90 is positioned in one of the notches 84, 85, or 86, thus preventing rotation of the shaft 57. When the shaft 98 is rotated to bring the cam 97 out of engagement with the tail piece 96, the nose 95 of the pawl is withdrawn by a helical tension spring 119. When this situation prevails, the operator can then rotate the shaft 57, effecting vertical movement of the guide rails 32. It is to be remembered however, that at this time the power circuit to the driving motor is opened. The operator can not effect reverse rotation of the shaft 98 until the guide rails have been moved from one running position to another, this resulting from the fact that the nose 95 of the pawl rides on the periphery of the disk 80 until one of the notches 84, 85, 86, is moved in registration with the nose piece, and while the nose piece is riding on the periphery of the disk 80, the tail piece 96 is maintained up against the low portion of the cam 97, thus preventing the cam and the shaft 98 from being rotated.

As previously explained, movement of the disk 80 from one notch to the next necessitates several turns of the shaft 57, and the arrangement of the gearing previously described, connecting the shaft 57 to the elevating screw nuts 48, is such that the guide rails 32 are properly adjusted. As previously explained, the nose piece 95 also engages the disk 82 and accordingly, when the cam lobe 83 of the disk is in engagement with the nose piece, it is not permitted to drop into any of the notches 84, 85 and 86. The reason for this arrangement is to permit the operator to make a fine adjustment, or to "trim" the posi-

tablishing the control circuit to the motor starter. After running a few cartons through the machine, he may conclude that the rails 32 need a very slight adjustment and if so, he can effect such adjustment by turning the shaft 57 within the close limits explained above and without the necessity of shutting down the machine.

Carton advancing mechanism

The cartons C are intermittently advanced along the guide rails 32 by a reciprocating rake mechanism positioned above each of the rails 32. Each of these rake mechanisms consists of a pair of rods 125 extending substantially the entire length of the guide rails and being provided at spaced intervals with members 126 having inwardly extending arms or teeth 127, 128, 129. A rectangular motion is imparted to these rake mechanisms, whereby they are moved inwardly to position the arms 127, 128 and 129 between the cartons positioned on the rails 32. The rake mechanisms are then advanced forwardly, advancing all of the cartons on the rails one step toward the right, Figures 1 to 3. At the end of this forward motion, the rake mechanisms are then moved laterally outwardly to move the arms 127, 128, 129, out of engagement with the cartons and thereupon the rake members are moved rearwardly, or to the left, a distance equal to the forward advancement. This operation is performed in repeated cycles, whereby the cartons are intermittently advanced in a procession along the guide rails.

Each rake mechanism is supported on three columns 130, 131, 132, mounted upon pads 141 and extending upwardly from the base 20. Housings 134, 135, 136, are slidably mounted upon the

cam is mounted upon a shaft 164 journalled in the column 131, as in bearings 165. This shaft is connected to a stub shaft 166 by means of a flexible coupling 167. The shaft 166 is journalled in the side wall of the main cam housing 22, see Figure 21, and is provided at its inner end with a beveled gear 168 arranged in mesh with a beveled gear 169 secured to the main cam shaft 24. With this arrangement, rotation of the cam shaft 24 effects vertical reciprocation of the rack 154.

The housings 134, 135, 136, are formed with transverse apertures to slidably receive rods 175, these rods extending perpendicular to the guide rails 32 and being secured at their inner ends to one of the members 126. In other words, the rack device, including the rods 125 and the members 126, are each supported by the three rods 175 extending inwardly from the housings 134, 135, 136. The rods 175 are formed with a central rack portion 176, see Figure 21. The rod 175 mounted in the central housing 135 engages one end of the pinion sleeve 141, see Figure 23. The sleeves 149 mounted in the end housings 134, 136, are also formed with a central pinion section 177, and the rods 175 mounted in these housings engage the pinion portion 177, see Figure 24.

It will be apparent that upon vertical reciprocation of the rack 154, the rod 175 and the rakes carried thereby are moved toward and from the guide rails 32, the rotary motion being transmitted from the sleeve 141 to the sleeve 149 through the shaft 143.

The lengthwise movement of the rake is effected by a cam 180 also mounted on the shaft 164 and formed with a cam groove 181. The housing 135 is provided with a rack 183 secured thereto by screws 184, see Figures 21 and 22. A gear 185 is journalled on a stud 186 in the column 131, the gear being arranged in mesh with the rack 183. An arm 187 is pivotally mounted at its lower end on a stud 188, and the upper end is formed with a gear quadrant 190 arranged in mesh with the gear 185. A roller 191 is adjustably secured to the central portion of the arm and is positioned in the cam groove 181. The arrangement is such that upon rotation of the shaft 164 and the cam 180, the housing 135 is reciprocated in a direction parallel to the guide rails 32, and this motion is, of course, transmitted to the end housings 134, 136, by the shaft or rod 143.

The cams 163, 180, and associated mechanism is so arranged and timed as to provide the rectangular movement of the rake mechanism previously referred to. The entire rake and rake actuating mechanism is the same on both sides of the machine, as will be apparent from a perusal of the drawings. During the period the rake is moving outwardly, rearwardly and inwardly, other parts of the machine are in motion to perform the various operations on the cartons.

From the description thus far, it is believed apparent that the machine embodies mechanism for intermittently advancing two rows or processions of cartons from left to right, Figures 1 and 3. The cartons are rectangular in cross section and open at the top, as shown in Figures 137 to 139. The cartons are deposited on the left end of the guide rails indicated at 192. The open ended cartons are made automatically by a carton making machine attached to the left end of the base 22 and operated in timed relation thereto, and which functions to deposit cartons at a position 193, Figure 3, and to alternately move

such cartons to the position 192 on the ends of the guide rails. In this position, the cartons are engaged by the rake mechanisms and advanced along the guide rails 32, as explained.

5 The carton engaging fingers 127, 128, 129, are so spaced along the shafts 125 as to receive the cartons between the fingers without any appreciable play or space between the cartons and the fingers. The inner ends of the fingers are slightly rounded at the corners to permit the fingers to readily move in between the cartons and, during the advancement of the cartons, they are engaged by the fingers on their rear sides but are also guided by the fingers on their forward sides, 15 whereby the cartons are maintained vertically and perpendicular to the guide rails 32. This arrangement permits the cartons to be advanced at high speed without agitating the contents of the cartons when they are filled with liquid, see Figure 28.

It will be observed that the fingers 127, 128, are shorter than the fingers 129, see Figure 21. When the guide rails 32 are in lowermost position, as shown in Figure 21, the carton advancing mechanism is operable to advance the tallest, or quart 25 cartons along the guide rails, in which instance all three of the fingers 127, 128, 129, engage the cartons. When the guide rails 32 are elevated to accommodate shorter cartons, as those of pint 30 capacity, the fingers 127 move below the outer edge of the guide rails 32, the fingers 128, 129, engaging the cartons. When the guide rails 32 are elevated to top position to accommodate the short 35 half-pint cartons, the fingers 127, 128, move below the outer side of the guide rails, and the cartons are advanced by the fingers 129.

Application of non-sealable material

40 The first operation performed on the advancing cartons is a pre-serving of a non-sealable material. Mechanism for accomplishing this result is mounted upon the left end of the machine and is designated generally at 200, Figure 1.

This mechanism consists generally of a housing 201 mounted on a supporting column 202 extending upwardly from the main cam housing 22. The housing 201 consists of a rectangular box with its long dimension extending substantially at 45° to the conveyor rails 32, see the plan view, Figure 28. In this instance, the non-sealing material consists of metallic foil arranged on spools 203 mounted on the top of the housing 201. The mechanism is operable to feed the end of the foil strip in juxtaposition to the top of a carton positioned under the mechanism, sever the end portion and fold it over the top edge at one corner portion of the carton. One of the purposes of the non-sealing strip, applied to the top of the carton, is to prevent the contiguous portion of the top closure from permanently sealing to the top of the carton, whereby that portion may be conveniently raised up, or separated, from the carton to provide an opening through which the contents of the carton may be poured.

65 The various mechanisms for applying the non-sealing material are actuated from a cam shaft 205 journalled in the housing 201 and extending lengthwise thereof. The shaft 205 extends through the front end of the housing and has secured to it a beveled gear 206 engaging a mating gear 207 secured to the upper end of a vertical shaft 208 journalled in the column 202. The lower end of the shaft 208 has secured to it a beveled gear 209 meshing with a mating gear 210 secured to the main cam shaft 24. With this ar-

angement, the cam shaft 205 is rotated in timed relation to the main cam shaft 24, see Figures 27, 33 and 35.

Two material applying heads, designated generally 212, Figure 28, are attached to the forward end of the housing 201, one end being positioned in register over one of the conveyor rails 32, and the other head also positioned over the other rail and accordingly, there are two spools 203 of the strip material. Both of the mechanisms 212 are identical, and reference will be made mainly to only one of the head mechanisms for purposes of description.

The strip material or foil 213 passes over an idler roll 214 downwardly and around a take-up roll 215 upwardly and over another idler 216, and downwardly into the head mechanism 212. The strip is advanced downwardly through the head between a feed roll 220 and a clamp roll 221. One of the heads 212 is mounted on a bracket 222 extending laterally from the upper end of the column 202, and the other head is mounted upon a similar bracket 223 extending laterally from the side of the housing 201. The heads consist of a plate 224 secured to the supporting brackets, as by screws 225. The major portion of the plate 224 is recessed from its rear end forwardly to accommodate various sliding members. An upwardly extending portion 226 is mounted on the forward end of the plate 224 and is apertured to slidably receive a vertically arranged pin 227. A lower guide block 228 is mounted on the plate 224 immediately to the rear of the member 226 and is secured thereto by screws 234, see Figures 39 and 42. An upper guide block 230 is positioned on the guide block 228 and is secured to the member 226. An outer strip guide plate 231 is mounted in spaced relation in front of the block 228, and a guide plate 232 is mounted in front of the upper block 230. The blocks 228, 230, and the outer guide plates 231, 232, are secured to the upright member 226 by screws 234 extending through the plates and blocks and threading into the member 226. The confronting central surfaces of the blocks 228, 230, and the plates 231, 232, are spaced apart to form a passage 238 through which the strip 213 is fed downwardly. This passage at the upper end of the head, indicated at 239, Figure 39, is substantially straight. However, as the passage continues downwardly, it is of V formation, with the angle of the V formation gradually decreasing to the angle shown in Figure 40.

The strip is fed downwardly through the passage 238 until the lower end of the strip is in proximity to a jaw 240, the forward end of which is spaced from a jaw 241 carried on an arm 242 pivoted at its upper ends in the member 226 on a pin 243, the arm yieldingly urging the jaw 241 away from the jaw 240 by a helical compression spring 244 mounted in a recess in the arm 242 and pressing against a plunger 245 engaging an anvil or shear block 246, see Figure 39. The face of the jaw 240 is formed with a V notch, and the face of the jaw 241 is of complementary V formation, see Figure 55. When the jaws 240, 241, are separated, a carton is elevated by a pedestal 248 to position a corner portion of the top edge of the carton between the jaws, with the top edge of the carton elevated thereabove, see Figure 57. When the carton is so elevated, the pin 227 is moved downwardly, engaging a cam surface formed on a projection 249 on arm 242, causing the arm to move clockwise about its pivot 243 and simultaneously, the jaw 240 is also moved toward the jaw 241. In this manner, the corner portion

of the carton is gripped between the jaws, see Figure 59.

The jaw 240 is slidably mounted on gibbs 250 secured to the under side of the plate 224, see Figure 29. A slide 251 is arranged immediately above the jaw and is recessed, as at 252, to receive a helical compression spring 253. The jaw is provided with a pin 254 having a portion extending upwardly into the recess 252. The compression spring 253 is interposed between the pin 254 and a similar pin 255 positioned in the slide 251. The forward movement of the jaw 240, relative to the slide 251, is limited by the pin 254 engaging the forward end of the recess 252, see Figure 39. Accordingly, when the slide 251 is advanced forwardly, the jaw 240 moves with the slide toward the jaw 241 until it engages the outer surface of the carton wall and thereafter, the spring 253 compresses during further forward movement of the slide. The slide continues forwardly until the front end 256 of the slide presses the severed portion 257 of the strip material against the outside of the carton. The forward end 256 of the slide 251 is also of V formation and is formed with forwardly extending projections 247 to retain the severed piece of foil in proper position.

The lower portion 257 of the strip 213 is severed by a cutting blade 258 attached to a slide 259, the blade cooperating with the confronting edge of the anvil block 246 of the bottom plate. The slide 258 has extending upwardly therefrom a knife support 260 to which is attached a knife 261. This knife is arranged to pierce the strip, the knife passing into a slot 262, see Figures 39 and 61. The relative position of the cutter blade 258 above the jaw 240, and the knife 261 above the cutter blade is such that the severed piece 257 of foil is provided with a slit extending upwardly from its lower edge forming a notch 427 in the outer fold 40 of the applied strip at the corner of the carton, see Figure 141.

When the depending portion 257 of the strip has been severed and clamped against the carton by slide 251, a slide 264 is moved forwardly to fold the upwardly extending portion of the severed piece over the top edge of the carton. The forward end of this slide is also of V formation, and a tucking finger 265 is arranged at the apex of the V and which serves to first fold over the apex portion of the strip, see Figure 63. When the remainder of the strip is subsequently folded over, this previously folded portion at the apex or corner of the carton, assumes a pleat or tuck formation at the corner of the carton. Thereafter, a folding jaw 266 is moved downwardly, folding the lateral portion of the strip snugly against the inner surface of the carton corner, see Figures 63 and 64. The downfolding jaw 266 is mounted on a slide 267 vertically slidable in a rectangular recess formed in the blocks 228, 230, the slide having a stem 268 extending upwardly through the top of the housing 226.

With the non-sealing strip, or material, now applied to the top edge of the corner portion of the carton, the pin 227 is moved upwardly and the slide 251 moved rearwardly separating the jaws 240, 241, see Figure 66. At this time, the slides 259, 264, are moved rearwardly. Thereafter, the downfolding jaw 266 is elevated, and the carton lowered on the pedestal 248, see Figures 67 and 68.

As previously stated, the lower jaw 240 is slidably mounted upon gibbs 250 secured to the under side of the plate 224 and, as stated, the plate 224 is recessed to slidably receive the slides 251, 259

and 264. The slide 251 is mounted upon the jaw 240. The slide 264 is mounted upon the slide 251, and the slide 259 mounted on the slide 264, the slide 259 being formed with a central rectangular opening 269 to accommodate the connection between the rod 295 and the slide 259. The plate 224 is also formed with an opening complementary to the opening 269, see Figures 39, 53.

The various mechanisms thus described are operated from the cam shaft 205 on which are mounted a series of cams 270, 271, 272, 273, 274 and 275. The cam 270 effects vertical reciprocation of a rod 280 connected to an arm 281 clamped to a shaft 282 extending transversely of the housing 201 and having attached to its ends an arm 283, the lower end of which is connected to the slide 251 by a link 284.

The cam 271 effects vertical reciprocation of a rod 285 connected to a link 286 clamped to a shaft 287, see Figures 27 and 28, having depending arms 288 connected to its ends, and the arms 288 are connected to the slides 259 by links 290.

The cam 272 effects vertical reciprocation of a rod 291 connected to an arm 292 clamped to a shaft 293. Arms 294 are clamped to the ends of the shaft 293 and are connected to the slide 264 by links 295.

The cam 273 effects vertical reciprocation of the rod 297 connected to an arm 298 clamped to a shaft 299. Arms 300 are secured to the ends of the shaft 299. On the front side of the machine, the arm 300 is connected to a leg 301 of a bell crank lever pivoted at 302 by a link 303. The arm 304 of the bell crank lever is connected to an arm 305 through a link 306.

The feed roll 220 is secured on a shaft 310 journalled at one end in a bearing 311, and at its opposite end in a bearing 312 mounted in a sleeve 313, the sleeve extending laterally outwardly from the block 230, see Figure 41. The arm 305 is in the nature of a bell crank, the other arm being 314, Figure 43, and the hub 315 of the bell crank is journalled on the outer surface of the sleeve 313. The outer end of the shaft 310 has secured to it a ratchet wheel 316, the teeth of which are engaged by a pawl 317 journalled on a pin 318 carried by the arm 305 of the bell crank. The pawl is urged in a counter-clockwise direction into engagement with the teeth of the ratchet wheel 316 by a compression spring 319 interposed between the pawl and a projection 320 carried by the bell crank arm 314.

With this arrangement, when the bell crank 305-314 is rotated about the shaft 310 in a counter-clockwise direction from the position shown in Figure 45 to the position shown in Figure 43, the shaft 310 and the feed roll 220 carried thereby are rotated to effect a downward feeding of the strip 213. The strip is held in engagement with the periphery of the feed roll 220 by the pressure roll 221. This roll is journalled in an arm 321 pivoted at its upper end on a pin 322 carried by the plate 232, the arm being yieldingly moved toward the plate by a compression spring 324 mounted on a screw 325 extending through the arm and being threaded into the plate 232, Figure 39.

On the rear side of the machine, the corresponding arm 300 extends horizontally to the shaft 299 and is connected directly to a corresponding link 306. The pull-down roll 215 is journalled on the end of an arm 328 of the bell crank lever pivoted at 329. The other arm 330 is connected to the arm 314 by a link 331. With this arrangement, the pull-down, or take-up

roll 215 is moved downwardly into the strip 213, unwinding a portion from the reel 203 during movement of the pawl 317 in a clockwise direction. During the strip feed operation, the roll 215 is moved upwardly, permitting the feed roll 220 to feed the slack established by the previous downward movement of the roll 215.

The cam 274 effects vertical reciprocation of a rod 336 connected to an arm 337 fixed to a shaft 338. This shaft extends in angular relation to the shafts 282, 287, 293 and 299. The shaft has secured to its ends arms 339 connected by links 340 to the rods 269.

The cam 275 effects vertical reciprocation of rods 343 connected to an arm 344 secured to a shaft 345, and to the ends of which are secured arms 346. These arms are secured to the pins 227 by links 347.

The rods 280, 285, 291, 297, 336 and 343 are mounted in supporting plates 350 extending transversely of the housing 201 and being detachably mounted on lugs 351, as by screws 352. These plates are formed with suitable bearing bosses 353. The lower ends of the rods are provided with yokes 354 slidably mounted on bearing blocks 355 journalled on the cam shaft 205 and being formed with opposed flat surfaces. Each rod is provided with a cam groove roller 356, see Figures 27 and 31.

Each spool 203 and its associated rolls 214, 215, 216, are mounted upon a bracket 360 attached to the housing 201, as by screws 361. There is also attached to each bracket a strip clamp consisting of a plunger 363 urged against the strip 213 by a helical compression spring 364 encircling the stem 365 of the plunger, the plunger and spring being mounted in an apertured boss 366 forming part of the bracket 360. A nut 367 is threaded on the outer end of the stem 365 and is engaged by an arm 368 secured to a shaft 369 journalled in the bracket. The shafts 369 are provided with arms 370 extending upwardly and connected together by an adjustable link 371.

The arms 370, associated with the spool structure on the rear side of the mechanism, form part of a bell crank lever, the other arm 372 of which extends rearwardly overlying a pin 373 slidably mounted in the housing for vertical movement. The lower end of the pin engages a lever 374 pivoted at its opposite end on a screw 375. Intermediate its ends, the lever is provided with a roller engaging the peripheral surface of the cam 274.

Normally, the plunger 363 clamps the strip against a portion of the bracket 360 under action of the spring 364. During the feeding of the strip, the pin 373 raises the arm 372, moving the arms 370 to the right, Figure 27, and moving the head of the plunger 363 outwardly against the spring 364, releasing the strip. The arrangement is such that the plunger 363 clamps the strip during the downward movement of the take-up roll 215, and during the movement of the shear 258.

In Figure 28, the cartons C are illustrated as being advanced below the heads 212, and as they leave the head, the foil strip is applied to a corner portion of each carton, as indicated at 376. Thus, each carton advanced below the heads 212 is preserved with the non-sealing material.

The mechanism just described for pre-serving the carton top with non-sealable material includes means which functions to prevent feeding and severing of the material in the event no carton is present below either head mechanism 212.

A carriage 380 is slidably mounted in the bottom portion of the column 202 on rods 381. The carriage moves parallel with the guide rails 32 and is yieldingly urged to the right, Figures 34, 35, by helical compression springs 382. The carriage is provided with a roller 383 engaging a cam 384 secured to the drive shaft 208. The cam is formed with a flat surface 385 which, when in engagement with the roller 383, permits the carriage to be moved under the influence of the springs 382. The cam 384 is also engaged by a roller 386 journalled on a pin 387 in a plunger 388 slidably mounted in a boss 389 formed in the inner wall of a switch box 390 detachably secured to one side of the column 202, as by screws 391. The plunger is urged toward the cam by a compression spring 392. A cross arm 393 is secured to the outer end of the plunger, and is provided at its ends with adjusting screws 294 engaging reset buttons of switches 395.

The carriage 380 is apertured to slidably receive rods 398 which carry at like ends arms 399 bifurcated at their lower ends to receive pins 400 carried by arms 401 secured to the lower end of shafts 402, these shafts being journalled at their lower ends at the lower portion of the column 202, and at their upper ends in a bracket 403, see Figures 33 and 36. The lower ends of the shafts 402 are split, as at 405. The portion on the shaft at one side of the slot 405 is threaded to receive a screw 406 which engages the material on the opposite side of the slot and expands the same in the bore of the arm 401. The outer wall of the column is provided with a threaded aperture to provide access to adjust the screw 406, the aperture being closed by a plug 407.

The shafts 402 are provided with enlarged portions 408, 409, 410, and each of these enlarged portions is formed with a notch to receive a latch 411 carried on an arm 412 pivoted in a bearing block 413 mounted in the channel member 36 of the conveyor rail structure. This arm has an upwardly extending portion 414 provided with a pin or projection 415 extending through the side member of the guide rail 32. The arm member is also formed with a portion 417 extending in the opposite direction and which is associated with mechanism to be hereinafter described for periodically oscillating the arm about its pivot to move the latch 411 toward and from the shaft 402.

When the carriage 380 is moved to the left Figure 34 under the influence of the cam 384, the carriage engages the arms 399, thereby moving the arms and the rods 398 to the left, Figure 34. This effects a counter-clockwise rotation of the shafts 402 through the pins 400 and arms 401. At this time, the notch in the enlarged portion 408 is positioned in register with the latch 411 and simultaneously, the arm 412 is moved toward the conveyor rail and if no carton is present to be engaged by the pin 415, the latch will move out of the notch, and when the flat surface 385 of the cam 384 engages the roller 383, the carriage will move to the right under the influence of the springs 382 and likewise, the rods 398 will be moved to the right under the influence of compression springs 420 mounted in caps 421 secured in the column 202, see Figure 35. The rods 398 will be permitted to so move to the right, Figure 34, and the ends of the rods will engage button 422 of the associated switch 395, actuating the switch to close the contacts thereof.

However, if a carton is present when the arm

75

412 is moved inwardly, the pin 415 will engage the bottom of the carton not permitting it to be moved in, and maintaining the latch 411 in the notch of the enlarged portion 408. When this situation prevails, the corresponding rod 398 will be held against return movement, and the corresponding switch 395 will not be actuated to closed position.

However, when no carton is present to be engaged by the carton detector pin 415, the switches 395 are closed and the associated solenoids 396 are energized. When this takes place, the armature 428 is moved upward against the roller 429 carried by the depending portion of the pawl 317, moving the pawl about its pivot 318 and holding the nose of the pawl out of engagement with ratchet 316, thereby preventing rotation of the strip feed roll 220 during the movement of the arm 305, see Figure 47. The shaft 310 and the ratchet 316 secured thereto, are yieldingly pressed against a friction washer 430 interposed between the ratchet and the outer end of the bearing sleeve 312. This is accomplished by a plunger 431 mounted in a bracket 432 mounted on the solenoid housing 397. The inner end of the plunger is pressed against the outer end of the shaft 310, on an antifriction ball 433, by a compression spring 434. The purpose of this structure is to minimize retrograde movement of the feed roll 220.

In addition to preventing rotation of the roll 220 and downward feeding of the strip 213, it is also desirable to prevent, in the absence of a carton, reciprocation of the shear blade 258 to positively eliminate the possibility of the blade shearing a small sliver from the lower edge of the strip. Mechanism to accomplish this result is disclosed in Figures 39-46 to 50.

The actuating link 290 has affixed to the end 40 thereof a member 435 having an upwardly extending portion 436 slidably mounted upon the link 295. The member 435 is bifurcated, and a latch 437 is pivotally mounted at one end to the member and is formed at its opposite end 45 with a depending hook portion 438 arranged to engage a pin 439 carried by a bifurcated member 440 secured to the shear slide 259. A latch 437 is secured to the pin 441 to the outer end of which is secured a depending member 442 having a laterally projecting pin 443. A bracket 444 is secured on the side of the head 224, as by screws 445. An angle arm is journalled in this bracket on a pin 446, the arm having an upwardly extending portion 447 and a rearwardly extending portion 448 formed with a hook 449. When the angle arm is moved in a counter-clockwise direction, Figures 47-49, the hook 449 is moved downwardly into the path of movement of the pin 443, and upon rearward movement of the link 290, engagement of the pin 443 in the hook 449 effects counter-clockwise movement of the latch 437.

The angle arm is moved about the pivot pin 446 when the solenoid 396 is energized. A rock shaft 450 is journalled in the solenoid housing 397. A laterally extending arm 451 is secured to one end of the shaft, and an upwardly extending arm 452 is secured to the inner end of the shaft. The arm 451 is connected to the lower end of the solenoid plunger 428 by a link 453. When the solenoid is energized and the plunger moved upwardly, the shaft 450 is rotated in a counter-clockwise direction, Figure 47, and the upper end of the arm 452 presses against the end of a rod 454 and urges the rod to the left,

21

Figures 46, 47. The opposite end of the rod is provided with a pair of spaced apart fixed collars 455 engaging a pin 456 on the upper end of the bell crank arm 447. The rod 454 is slidably mounted in a bracket 457 also secured to the side of the head 224, as by screws 458.

It will be understood from the description previously that the shear blade plate 259 moves the shear 258 into shearing relation with the anvil 246 when the shear plate is moved forwardly, or to the right, Figures 39, 47, and this shearing action takes place after the strip 213 has been fed downwardly, the feeding action being initiated by the presence of a carton, one position ahead of the pedestals 248. If no carton is present in that position to be engaged by the detector element 412, the solenoid 396 is energized. This, of course, previous to the full return of the link 290 and energization of the solenoid results in the hook 449 being moved downwardly to be engaged by the pin 443 during the last part of the return movement of the link 290 and accordingly, effects movement of the hook portion 438 upwardly, as shown in Figure 47. With the latch 437 in this position, the next forward movement of the link 290 will cause the latch to move over the pin 439 and inasmuch as the notch in the latch 437 does not engage the pin 439, there will be no forward movement of the shear slide 259.

The time that the switches 395 are energized and before which they are reset by the cam 384 is relatively short, and the push rod 454 is urged to the right, Figure 47, by a helical compression spring 461 interposed between the bracket 457 and a collar 462 secured to the rod. Accordingly, as soon as the solenoid 396 is deenergized, the spring 461 urges the bell crank lever about its pivot 446 in a clockwise direction. However, the tail portion 463 of the hook 449 is of sufficient length to engage the pin 443 during the initial forward movement of the link 290, see Figure 48, and thus keep the latch 437 in up position until after the rear edge of its notch has reached the center of the pin 439.

If a carton is present on the guide rail to be engaged by the pin 415 of the detector arm 412, the solenoid 396 is, of course, not energized, and the bell crank remains in the position shown in Figure 49 with the hook 449 positioned above the path traveled by the pin 443 and accordingly, with the notch of the latch 437 engaged over the pin 439 to effect reciprocation of the slide plate 259 upon reciprocation of the link 290.

When the switches 395 have been actuated to closed position by the absence of a carton in the procession being advanced along the guide rails 32, the switches remain closed until the flat surface 385 of the cam 384 engages the roller 386 on the plunger 388, permitting the plunger to move the member 393 into engagement with the reset buttons on the switches. This period, during which the switches 395 are closed and the solenoids 396 are energized, is sufficient to prevent feeding of the foil strip during the succeeding advance movement of the carton advancing mechanism.

This mechanism just described is effective to prevent any movement of the strip shear during times when no cartons are presented to the pedestals 248.

Carton detection and elevating mechanism

Referring to Figure 4, a cam 470 is secured on the main cam shaft 24 toward the right hand

22

end of the machine. A pad 471 is mounted on the base section 20 below the cam, as by screws 472. A reciprocating slide 473 is mounted on the pad and is provided with a roller 474 engaging the groove 475 in the cam 470. With this engagement, the slide 473 is reciprocated lengthwise of the shaft 24 upon each revolution of that shaft, the slide being retained in a recess in the pad 471 by gibbs 476 attached to the pad by screws 477, see Figures 69, 71 and 72.

A pair of gear quadrants 478 are journaled on studs 479 carried by plates 480 secured to the cam housing 22, as by screws 481. The inner ends of the quadrants 478 are provided with rollers 482 positioned in a transversely extending slot 483 formed in the slide 473. The outer ends of the quadrants are formed with gear teeth 484 arranged in mesh with pinions 485 secured to the lower ends of shafts 486 journaled in sleeves 487 mounted in the cam housing 22, as by screws 488. The shafts 486 extend upward from the sleeves 487 through concavities 489 formed in the sides of the cam housing. The upwardly extending portions 490 of the shafts are square in cross section and terminate just above the top wall of the cam housing. The shafts are restrained against downward movement by collars 491 overlying the top of the sleeve 487, or a bushing carried thereby. The pinions 485 engage the lower end of the sleeves and are secured in place by nuts 492.

Directly above each of the shafts 486 there is mounted in the supporting channel 36 of the guide rails 32 a block 494. This block has journaled in it a vertical shaft 495 and a pinion gear 496 is secured to the shaft intermediate the ends thereof. A cap 497 is secured to the lower ends of the shafts 495, as by nuts 498. The caps 497 are threaded externally to receive a collar 499. This collar is formed with an internal shoulder engaging an annular shoulder 500 formed on the upper end of a sleeve 501. The caps 497 are formed with an annular series of projections 502, and the shoulder 500 of the sleeve 501 is formed with complementary interlocking projections 503, see Figure 70. This structure provides detachable, adjustable and positive drive connection between the sleeves 501 and the shafts 495. The lower end of this sleeve, as indicated at 504, is provided with a square bore to slidably receive the square upper portion 490 of the shafts 486. With this arrangement, rotary motion of the main cam shaft 24 imparts oscillatory motion to the shafts 495, and the arrangement described permits vertical movement of the guide rails 32 for and in the manner previously explained.

The blocks 494 are apertured parallel to the guide rails 32 to receive racks 505, rods 506. The racks 505 are formed with gear teeth 507, see Figure 74, arranged in mesh with the pinion 496, whereby upon rotation of the pinion lengthwise movement is imparted to the racks 505. The racks have secured to their ends clamp members 508 clamped to the rods 506, as by screws 509, see Figure 73, whereby reciprocation of the racks 505 effects reciprocation of the rods 506.

The rods 506 extend in the channel members 36 to the right from the blocks 494 through blocks 510, see Figures 73, 74. The rail structures continue on to the right end of the machine and there is another block similar to the block 510. In each of the blocks 510 there is vertically mounted a stem 511, these stems carrying pedestal pads 512, 522, at their upper ends, see Figure 3. The rods 506 also extend to the left substan-

tially the entire length of the machine, see Figures 75, 76, 77 and 78, in that order.

Referring to Figures 77, 78, the left hand ends of the rods 506 are slidably supported in bosses 514 depending from the bearing block 413 secured in the channel formation 36, as by screws 516. A cam block 517 is clamped to the rod 506 intermediate the bosses 514. The block 413 is formed with a vertical bore in which the intermediate portion of the detector lever 412 is journaled, and the rearwardly extending portion 417 of the detector lever is provided with a roller 518 engaging the cam 517. The block 413 is apertured at 519 to receive a compression spring 520 which urges the arm 417 inwardly to maintain the roller 518 into engagement with the cam 517. Accordingly, when the rod 506 is moved to the left, Figures 77, 78, the arm 417 is moved inwardly by the spring 520 causing the arm 412 to move toward the guide rail 32, moving the pin 415 through the side of the guide rail and into engagement with a carton positioned on the guide rail. If no carton is present, the arm 412 will move inwardly far enough to move the detent 411 out of engagement with the enlarged portion 408 of the shaft 402. However, if during this operation a carton is present on the guide rail 32, the pin 415 will engage the bottom of the carton, and the spring 520 will not effect oscillation of the angular lever because of the engagement of the pin with the carton and, of course, will not move the detent 411 out of the notch in 408.

As previously explained, when this situation prevails, the strip material will be fed downwardly through the strip applying head for application to that carton, and the shear blade will operate. However, if no carton is present, the latch 411 will be moved out of engagement with 408, interrupting the strip feed and strip shear.

The rod 506 also imparts vertical movement to the pedestals 248, and also to the pedestals 512 under the first sealing head, the pedestals 522 under the second heads, and the pedestals 523 under the end closure forming and applying heads. All pedestals are operated simultaneously and embody the same structure. Accordingly, reference need only be made to the structure and operation of the pedestals 248. The pedestals 248 are arranged on the upper end of square stems 524 mounted for vertical movement in blocks 525, similar to the blocks 510, also secured in the channel structures 36. These blocks are apertured to slidably receive sleeves 526 through which the rods 506 extend. The sleeves 526 are restrained against axial movement on the rod in one direction by collars 527 clamped to the rods. In the opposite direction, the sleeves are restrained by helical compression springs 528 encircling the rod and engaging a similar clamp collar 529, the confronting surfaces of the collar and block 524 being recessed to receive the spring. The under side of the sleeve 526 is formed with a gear rack 530 arranged in mesh with a pinion 531 journaled in the blocks 525 on stud 532, and also arranged in mesh with a rack surface 533 formed on the stem 524.

With this arrangement, when the rod 506 is moved to the left Figure 78, the sleeve 526 is moved in the same direction by the clamp collar 527, the pinion 531 is rotated in a counter-clockwise direction, and the stem 524 elevated, moving the carton upwardly into the strip applying mechanism. When the rods 506 are moved to the right, the sleeves 526 are urged in the same direction by the springs 528 effecting

downward movement of the pedestal stems 524. This downward movement continues until the pedestal plates seat in the guide rails 32. The spacing between the collars 527, 529, is somewhat greater than the length of the rack 526. This permits some over travel of the rods 506, as shown by the space 536 between the end of the rack and collar 527 in Figure 78, when the pedestal is seated in the rail. The pedestal plates 248 are secured to the stems 524, as by bolts 538, see Figure 80. The push rods 506 are slidably mounted in a number of spaced bearing blocks 514 arranged in the channel formation 36 and in a similar manner operate a series of carton detectors shown in Figures 75 and 76. The operation of this portion of the mechanism can more appropriately be specifically described further on in connection with other mechanisms of the machine.

The structure thus far described is operable to advance a succession of cartons along each of the guide rails 32 and during such advancement, a non-sealing material is applied over the top edge at a corner portion of each carton at the station indicated by the pedestal 248. As the cartons are advanced along the guide rails to the right, Figure 1, they are filled by filling mechanism indicated generally at 540. This mechanism is mounted on the top of the cam housing 22 and occupies approximately a space indicated by the outline of the pad 541, Figure 3, which extends from the strip applying mechanism to approximately the center of the machine.

The filling mechanism is supported by a column 542 mounted upon the cam housing 22, and the mechanism is operated by various cams 543, 544, 545, 546 and 547, mounted upon the main cam shaft 24. The liquid is supplied from a tank or reservoir 548 mounted above the filling mechanism. The filling mechanism forms no part of this invention and accordingly, it is not described in detail.

Top closure application

When the open ended cartons have been advanced along the guide rails 32 to the pedestals 523, the cartons are elevated by these pedestals, and conditioned top closures are applied to the tops of the cartons. These top closures are formed from flat blanks 616 arranged in stack formation in a tubular magazine 615. As each carton is advanced beneath the filling mechanism 540, a blank is withdrawn from the magazine 615, inserted in blank carriers on a conveyor and conveyed through a heating oven 678. When the heated blanks reach a position above the pedestals 523, they are transferred into a forming and applying head 677 shown in Figure 102. This head is operable in a succession of operations to form the blank into an end closure and insert the same in the open end of a carton.

A column 554 is mounted upon the cam housing 20, the upper portion of which projects laterally on either side, as at 555, see Figures 85, 88. A bracket 556 is attached to the face of each of the projecting portions 555 and serve as supports for housing 557. These housings are spaced outwardly from the column sections 555 to provide a space 558 in which the blank conveyors are mounted. The housings 557 are partially supported by tubular columns 559 extending upwardly from the top of the base 20.

The blank conveyor consists of an endless chain structure trained over a pair of sprockets located

in the space 558. A shaft 560 is journalled in a boss 561 extending inwardly from the housing 557 at one end thereof. The inner end of the shaft 560 is provided with a cup-shaped hub member 562 encircling the boss 561 and on which there is mounted a pair of sprocket wheels 563. The sprockets 563 are mounted on a split hub 564, as by screws 565, the hub 564 being clamped on the hub 562.

The outer end of the shaft 560 is provided 10 with a gear 566 arranged in mesh with an idler gear 567 mounted on a stud 568 journalled in antifriction bearings, one of which is mounted in the back wall of the housing, see Figure 96, and the other in a front plate 569 detachably secured to the front of the housing, as by cap screws 570, the outer bearing being retained in the cover plate by a cap 571. The gear 567 is arranged in mesh with a gear 572 mounted on a stud 573 also journalled in bearings mounted in the back wall 20 of the housing and the cover plate 569, the outer bearing being retained in place by a cap 574.

The gear 572 has affixed to it a Geneva disk 575. The slots 576 of which are engaged by a crank pin 577 carried by a crank arm 578 secured to shaft 579, see Figures 92, 96. The shaft 579 is journalled in a bearing mounted in the inner wall of the housing 557 and in a bearing mounted in a cap 580 secured to a boss 581 formed on the cover plate 569.

The shafts 579 extend inwardly across the spaces 558 and into sections 555 of the housing 554, see Figure 88. The inner ends of the shafts are coupled to a shaft 584 journalled in the central portion of the housing 554 by coupling 585. A gear 586 is secured on the shaft 584 and is arranged in mesh with a gear 587 secured on the upper end of a shaft 588 journalled vertically in bearings 589 in the housing 554. This shaft is provided at its lower end with a gear 590 arranged in mesh with gear 591 secured on the main cam shaft 24, see Figures 4, 88 and 89. With this arrangement, the shaft 579 is rotated from the main cam shaft 24 and upon each revolution of the shaft, the Geneva sprocket 575 is indexed $\frac{1}{8}$ of a revolution, and the sprockets 563 are rotated one-quarter of a revolution through gearing 566, 567, 572. The forward wall of the housing 557 is formed with a square aperture in which is slidably mounted a stem 595 of a sprocket carrying arm shown in Figures 94 and 95. The forward portion of this arm is formed with spaced apart walls 596 from which projects studs 597 which carry bearings 598 on which are mounted sprockets 599. The arm is yieldingly urged forwardly by a helical compression spring 603 mounted in a recess 601 formed in the stem portion 595, the rear end of the spring pressing against a pad 602 retained in place by a pin 603 extending transversely of the arm through slots 604 and secured in the forward wall of the housing. A chain 605 is trained over corresponding ones of each pair of sprockets, see Figures 93, 96. The purpose of the spring 600 is to maintain the chains 605 taut.

At spaced intervals, the chains 605 are provided with lugs 607 to which are secured blank carrying members. These members consist of sheet metal stampings having depending sides 608 connected by transversely extending parts 609. The side portions 608 are secured at each end to lugs 607 by pins 610. The apertures in like ends of the side pieces 608 are formed with elongated slots 611. A blank engaging member 612 is secured to each cross member 609. These blank

carrying members are somewhat Z shaped in cross section. That is, the outer edges of the members are formed with blank receiving notches 613, and these notches are arranged in confronting relationship so that the spaced apart members 612 frictionally receive opposite edges of the blanks 614. The purpose of the elongated slots 611 is to accommodate the difference in spacing between the lugs 607 as the carriers travel around the sprockets 563, 599, see Figure 92.

As previously stated, the flat end closure blanks 614 are arranged in stack formation in the magazines 615 which are mounted on supporting rods 616 extending upwardly from the forward end of the housings 557 at an angle of approximately 45°. The blanks are successively withdrawn from the magazines 615 and deposited snap-fashion between the pairs of blank carrying members 612 by a reciprocating blank feeder 617 provided at its upper end with a suction cup 618 of rubber, or like material. The feeder 617 is slidably mounted in bosses 619, 620, constituting part of the sprocket supporting arm shown in Figures 94, 95, the bosses being arranged intermediate the sides 596 of the arm and being apertured to permit the feeder 617 to slide parallel to the axis of the blank magazine 615, see Figures 93, 97. The feeder 617 is actuated by a cam 622 mounted on shaft 579. The periphery of this 30 cam engages a roller 623 mounted on an arm 624. This arm is journalled at its upper end on a stud 625. The lower end of the arm is pivotally connected to a link 626, the opposite end of which is pivotally connected to a member 627 clamped to the feeder stem 617 intermediate the bearing bosses 619, 620. Upon rotation of the cam 622, the feeder is thus caused to move the suction cup 618 upwardly into engagement with the lowermost blank in the stack, as indicated by the dotted outline Figure 97, and then downwardly to the full line position shown in that figure.

It will be observed that the feeder member operates between the chains 605 and also between the transversely extending parts 609 of the blank carriers. In this downward movement, opposite side edges of the blank 614 engage the outer ends of the carriers 612, causing the center portion of the blank to flex downwardly until the edges of the blank enter the notches 613. That is, the blank is inserted in the carriers 612 snap-fashion. It will be understood that the arrangement of the Geneva drive 575, 578, Figure 92, and the cam 622 is such that the blank feeder 617 is operated during the dwell period of the conveyor chains 605. When the feeder is in the down position, as indicated in Figure 93, the chain conveyor may be actuated or indexed.

The suction cup 618 is secured to the upper end of the stem 617 by a screw 630. This screw is apertured in registration with an aperture 631 extending axially of the stem 617, the lower end of the aperture being connected to a fitting 632 which, in turn, is connected by a hose or flexible conduit 633 to a source of vacuum. The stem 617 is also formed with a laterally extending aperture 634 communicating with the aperture 631 and extending radially outwardly through the clamp member 627. This clamp member is formed with a boss 635 which is formed with a bore extending parallel to the stem and with which the aperture 634 communicates. The lower end of the bore is provided with a valve seat 636 to receive a ball check 637 normally held in engagement with the valve seat, and thereby closing the same,

by a helical compression spring 638, the upper end of which presses against a closure plug 640.

The bottom boss 620 is formed with a lateral projection 641 carrying a threaded stud 642 arranged in register with the aperture in the valve seat 636 and adjusted so that when the blank feed stem 617 is in down position, the stud 642 raises the ball check 637 off from the seat 636. This arrangement connects the passage 634 to atmosphere and breaks the vacuum. When the stem 617 is moved upwardly by the cam 622, the ball check 637 is seated on the valved seat shutting off the connection to the atmosphere and providing vacuum in the suction cup at the time it engages the lowermost blank 614 in the stack. Thus, the blanks are successively withdrawn from the magazine 615 and deposited in the blank carrying members.

The magazine 615 is in the nature of a rectangular tube to accommodate the rectangular blanks 614, and is provided with a door 645 on its upper side to permit the magazine to be conveniently loaded with blanks. The magazine tube is secured to a casting 646 formed with apertures to receive the supporting rods 616 which are carried by a bracket 647 formed with a depending flange 648 overlying the forward portion of the housing 557. This flange is formed with a plurality of elongated apertures 649 to receive mounting screws 650 threaded into the housing. With this arrangement, the bracket 647, and the magazine 615 carried thereby, can be adjusted lengthwise of the blank conveyor chains so that the bottom of the magazine can be arranged in proper alignment with the blank carriers 612.

The magazine tube is slightly greater in cross sectional dimension than the blanks, so that they will freely feed to the bottom of the magazine tube by gravity. The underside of the magazine tube is formed on its inner surface with a pair of spaced apart ribs 651. Opposite side walls of the tube are formed with ribs 652 which extend a distance upwardly from the lower end of the tube. A rib 653 is also mounted on the top wall below the door. The ribs 652, 653 are of taper formation, the thickened ends of the ribs terminating in proximity to the lower end of the tube, see Figure 93. The inner surface of the door 645 is provided with a straight rib 654. The ribs 651, 654 serve to reduce the frictional engagement of the blanks with the magazine tube to a minimum, whereby they will freely move downwardly in the tube. The purpose of the tapering ribs 652, 653 are to accurately center, or position, the blanks at the discharge end of the magazine.

The blanks are supported in the magazine by horizontally extending members 655 mounted on the inner surface of the top and bottom walls of the tube at the bottom end thereof, see Figure 97. Preferably, the ribs 655 are formed on their confronting surfaces with grooves 656 to minimize withdrawing two blanks at a time from the magazine by the suction cup 618, as previously explained.

The blank conditioning mechanism includes means for stopping the operation of the machine in the event more than one of the blanks 614 is withdrawn from the magazine by a single operation of the blank feed 617. The bracket 647 is formed with a box portion open on the top and the side, these openings being provided with closures 658, 659, respectively. A switch 660 is mounted in the box and is connected in the holding circuit of a relay 661, see Figure 136. This

relay effects closing of the starter 662 for the drive motor 28. The contacts of the switch 660 are normally closed, the switch being actuated to open position by an arm 664 mounted on a shaft 665 journaled in the side walls of the switch box and extending through the inner wall of the box and being provided at its inner end with an arm 667. The arm 667 is located in the space 558 in which the conveyor chains travel, the arms 664, 667, both extending rearwardly. The free end 668 of the arm 667 is offset inwardly toward the adjacent sprocket 599 and positioned over an anvil 669 extending inwardly from the inward wall of the switch box, see Figures 98, 99 and 100. The arm 667 is yielding urged downwardly toward the anvil by tension spring 670, the end 668 of the arm being maintained in spaced relation above the anvil 669 the thickness of one blank 614 by an adjustable stop screw 671 threaded into the bottom wall of the switch box and engaging the free end of the arm 664. The arrangement is such that the side portion of each of the blanks 614 passes between the anvil 669 and the end 668 of the arm 667. If there is one blank in the holders 612, no movement is imparted to the arm 667 and therefore, no movement is imparted to the arm 664. However, if two or more blanks are positioned in the holder, the arm 667 is moved upwardly, rocking the shaft 665 and moving the arm 664 upwardly. This arm carries in its central portion an adjustable switch contact screw 672 which engages the actuating button of the switch 660 effecting a separation of its contacts, 35 opening the circuit to the holding relay 661, permitting the motor starter 662 to open the power circuit to the driving motor 28 and thus stop the machine and afford the operator an opportunity to remove the excess blanks from the holder. The switch 660 is preferably of the type that must be reset manually, and the top closure 659 is provided with a reset button 673.

The upper run of the chains 605 travel rearwardly, or to the left Figures 84, 92, 93, through a horizontal passage 675, the rear end of which communicates with an arcuate passage 676 and as the blanks leave the passage 676 and reach the position indicated at T, Figure 93, the blanks are transferred from the carriers into the forming and applying heads designated generally 677, Figures 86, 87, 102.

The blanks 614 are coated, at least on their upper sides, when stacked in the magazine 615, with a thermoplastic adhesive. As the blanks 55 are advanced from the magazine toward the station T, they are moved in close proximity to a heater 678. These heaters are secured to castings 679. The castings 679 are secured to the ends of a shaft 680 which extends transversely of the machine and which is journaled at its ends in bosses 681 formed on the brackets 647. The heaters 678 serve to properly heat and condition the blanks and the coating thereon so that the blanks may be subsequently formed into end closures and applied to the tops of the cartons. The passages 676 may be heated by heating elements 682, as shown in Figure 93, the purpose of which is to maintain the blanks at proper conditioned temperature until they reach the transfer position T. The primary purpose of the heaters 678 is to sterilize the blanks 614 before their application to the tops of the cartons. In some instances, the blanks may be coated with material which permits forming the blank more advantageously when it is heated. The heaters

therefore further serve in such instances to condition the blanks for forming.

The machine includes means operable to prevent withdrawal of a blank 614 from the magazine 615 in the event a carton is absent in the procession being advanced by the rake 125. As previously explained, the suction cup 618 is moved upwardly into engagement with the lowermost blank in the magazine 615 by the cam 622 actuating the lever 624, Figure 93. In normal operation, the blank feeder is operated upon each revolution of the shaft 579. In the event there is no carton in the advancing procession to receive a top closure, a pin 684, slidably mounted in bracket 559, is moved into the path of a projection 685 carried by the arm 624 when the suction cup 618 is in its lowermost position. The arm 624 is moved to the right, Figure 93, to actuate the cap feeder by the spring 686. Accordingly, when the pin 684 is moved into the path of the arm 624, the arm is not permitted to follow the contour of the cam 622 under the influence of the spring 686.

The pins 684 are moved into the path of the arms 624 by solenoids 687 located in the housings 555, see Figures 88, 96. The solenoids, when energized, are operable to move the pins 684 outwardly from the column 554, Figure 88, the pin being yieldingly maintained in either the in or out position by a detent 688 mounted in the bracket 558. The pins 684 are moved inwardly, or reset, each revolution of the cam 622 by a cam surface 629 formed on the inner side of the cam 622, see Figures 88, 96.

The solenoids 687 are respectively energized by switches 690, the leads 691 of these switches being connected in circuit with the solenoids 687 respectively, see Figure 122. The switches 690 are located in a box 692 mounted on the end of the filler column 542. In connection with describing the structure for applying the non-sealable strip material to the tops of the advancing cartons, reference was made to mechanism operable to effect feeding of the strip material as each carton was advanced. This mechanism included the arms 412, Figure 77, these arms having pins or projections 415 movable over the guide rail 32 in the path of the advancing cartons. These arms 412 were oscillated about their pivots by the push rods 506. At the filling station, there are arranged in each conveyor rail a group of similar arms 694, 695, 696, 697 and 698. It is to be kept in mind that the conveyor mechanism advances two processions of cartons and accordingly, most of the mechanisms are arranged in duplicate.

The detector arms 694, 695, 697 and 698 are used to actuate the filling mechanism, that is the milk, or other liquid, is dispensed into the cartons at four successive stations. These arms are also all actuated by the push rods 506, see Figures 75, 76, and each of the arms is provided with a rearwardly extending portion 699 provided with a pin 700 which is movable into and out of the path of the advancing cartons. The arm 696 does not have any portion 699. The arms 694, 698 are journaled in bearing blocks 413 and, with the exception of arm 696, are formed with arms 701 having rollers 702. The arms 701 correspond to arms 417 in the carton detector mechanism associated with the strip applying means. These rollers 702 engage cams 703 mounted on rods 506 similar to the cams 511. The arms 694, 695, 697, 698, are actuated about their pivots to move the pins 700 into the

path of the advancing cartons by springs 704 corresponding to the springs 520. That is, when the push rod 506, Figures 75, 76, is moved to the left, the springs 704 cause the rollers 702 to follow the cams 703, permitting the arms 701 and their associated arms 694, 695, 697 and 698 to move counter-clockwise. If no carton is present at any of the stations to be engaged by a pin 700, the inward movement of that arm 699 is sufficient to move the latch portion 705 of the corresponding arms 694, 695, 697, 698, out of the notch in the enlarged portion 706 of the associated shaft 737. If a carton is present and is engaged by the pin 700, the corresponding arm is not oscillated about its pivot by the spring 704 and accordingly, the latch portion 705 is not moved out of the notch in the corresponding shaft.

Referring to Figures 75 and 76, it will be observed that the arm 696 does not have a portion 699 extending to the left with a detector pin 700. This arm is actuated by the adjacent arm 695, which is formed with an outwardly extending portion 710, and the arm 696 is formed with a corresponding extending portion 711. These portions are connected by links 712, 713. In other words, the arm 696 is operated in unison with the arm 695.

A rod 715 is arranged adjacent each side of the column 542 near the bottom thereof. These rods are reciprocated lengthwise of the machine by a yoke 716 pivoted between its ends to a block 717 secured to a slide 718, as by screws 719. The slide is mounted for reciprocation in supporting members 720 mounted in the top of the cam housing 22. The slide is provided with a roller 721 positioned in a cam groove 722 formed on the periphery of the cam 723 which is mounted upon the main cam shaft 24, see Figures 4, 121 to 124 inclusive.

Each of the rods 715 has fixedly secured to it collars 725, and a series of collars 726 are slidably mounted upon the rods 715. These collars are yieldingly held against the fixed collars 725 by helical compression springs 727, see Figure 123. The collars 726 are formed with transversely extending depressions 728 on their upper and lower surfaces. There are a series of shafts 729, 730, 731, 732 and 733 journaled vertically in the housing 542. Each of these shafts is provided at its lower end with a hub 734 having an arm portion 735 extending into the recess 728 in the under side of the adjacent collar 726. The shafts 736, 737, 738, 739 and 740 are journaled vertically exteriorly of each side of the housing 542 and are provided with the notched enlarged portions 706.

A hub member 741 is secured to the lower end of each of these shafts respectively, and each hub has an arm 742 positioned in the upper recesses 728 of the corresponding collars 726.

With this arrangement, when the yoke 716 is moved to the right, Figure 123, by the cam 723, the rods 715 and all of the collars 725, 726, are likewise moved. This movement effects oscillation of the shafts 736—740 through the arms 742, and oscillation of the inner shafts 729—733, through the arms 735. Upon further rotation of the cam 723, the yoke 716 and the rods 715 are moved in the opposite direction, and the collars 726 are yieldingly urged in that direction by the springs 727. When the yoke 716 and the rod 715 are moved to the right, Figure 123, the push rods 506 are also moved to the right Figure 75, and the latch portions 705 of the arms 694—

698 enter the notches in the shafts 736—740. When the yoke 716 and the rods 506 are moved in the opposite direction, or to the left, and any of the pins 700 engage cartons during this movement, the corresponding latch portions 705 will not move out of the notches in the shafts 736—740, but will latch these shafts against retrograde rotation. When the rods 715 move to the right, the inner shafts 729—733 are rotated in a direction opposite to that of the respective associated shafts 736—740. Upon return movement of the yoke 716, the collars 726 will be moved to the left effecting rotation of the shafts 729, 733 and 736, 740 in the opposite direction. However, in regard to any of the shafts 736—740 that are latched, as explained above, the associated collars 726 will be held against return movement and the associated spring 727 will be compressed. Inasmuch as the collars 726 are thus held against retrograde movement, likewise the shafts 729—733 associated with such collars are held against retrograde rotation. It will be apparent, on the other hand, that if the pins 700 on any of the arms 699 do not engage cartons, the associated latch portion 705 will have moved out of latching engagement and, on the return movement of the yoke 716, the shafts 729—733 will be rotated in the opposite direction. The inner shafts 729, 730, 732 and 733 control the dispensing mechanism of the filling structure. The shafts 731 have affixed to their upper portions a hub 745 to which there is pivotally connected a rod 746. These rods extend lengthwise along the inner surfaces of the side walls of the housing 542 and project into the switch boxes 692, and are provided at their ends with switch actuating elements 747.

Referring to the forward side of the machine, cartons being advanced along the guide rail 32 on that side of the machine will be engaged by the detector pin 700 of the detector arm 699. If there is a continuous procession of cartons, there will always be a carton present to be engaged by the respective pin 700, preventing movement of the latch portions 705 out of the notched enlarged portions 708 of the shafts 736—740. Accordingly, the rod 715 in the lower left portion of Figure 121, corresponding to the forward side of the machine, will always remain in shifted position to the right, with the control shafts 729, 733 having been oscillated in a counter-clockwise direction and these shafts will, of course, remain stationary. With this situation prevailing, the rod 746 will have been moved to the right, Figures 122, 124, and will remain there with the switch actuating element 747 out of engagement with the switch 690.

In the event there is a carton missing in the procession, the arms 694, 695, 967 and 698 will be permitted to oscillate about their pivots successively as the empty space in the procession occurs at each of the pins 700. When the arm 695 is thus permitted to be oscillated, the adjacent arm 696 will likewise be oscillated through the linkage 712, 713, causing the latch portion 705 of the arm 696 to be moved out of the notch in shaft 738 and, as the return movement of the yoke 716 is effected by the cam 723, the collar 726, associated with the shaft 731, will be moved under the influence of the associated spring 727, effecting clockwise rotation of the shaft 731 (lower portion of Figure 123). This will permit the rod 746 to move to the left, closing the associated switch 690 by engagement of actuating element 747. This completes a circuit to the

solenoid 687, Figures 88, 89, moving the latch pin 684 in interference with the arm 624 and thus preventing operation of the top closure blank feeder.

5 Accordingly, when the blank space in the procession arrives at the pedestal 523, there will be a corresponding blank space in the top closure blank conveyor. In other words, a bottom closure blank 614 is withdrawn from the magazine 615 for each carton present in the procession being advanced on the guide rails 32, and the particular carton which was engaged by the pin 700 of the carton detector arm 699, associated with the arm 695, will receive that top closure blank. On the other hand, if there are any interruptions in the procession of cartons, corresponding top closure blanks will not be fed from the magazine.

As previously stated, there are two carton 20 guide rails 32, along each of which there is advanced a procession of cartons. Accordingly, there are duplicate mechanisms for applying the non-sealable material to the carton top, applying top closures to the carton tops, and sealing 25 the closures to the carton tops, there being a set of these carton processing mechanisms arranged above each guide rail. The mechanisms above each rail are controlled by cartons being advanced on that rail. These are, therefore, 30 in the structure described two series of the inner shafts 729—733, and two series of the outer shafts 736—740, whereby the cartons of one procession are handled and processed independently of the cartons of the other procession.

Forming and application of top closures

The blanks 614 are transferred from the carrying members 612 when the blanks are positioned in the position T shown in Figures 92 and 93. 40 The blanks are transferred into a forming and applying head shown in Figures 102 and 103. These heads consist of a frame having a rear wall 750, and side walls 751. A head is mounted upon each lateral extension 555 of the column 554 with the heads positioned over the respective carton guide rails 32 and in registration with the carton elevating pedestals 523. A plate 752, having a central rectangular aperture, is secured to the bottom of the frame as by screws 753, the plate being accurately positioned on the bottom of the frame by dowels 754. The plate 752 is recessed to receive four die sections 755, on the peripheral margins of which is mounted a blank guide plate 756, both of these 55 plates being secured to the bottom plate 752, as by screws 757. The die sections 755 are formed to provide a central aperture of rectangular formation and being approximately the dimension of the inside of the carton, see Figure 60 116. Each section of the die is formed with a slot 758, and each section is relieved at one end to form a similar slot 759 with the end of the abutting section. The upper guide plate 756 is also formed with complementary slots 760 arranged in register with the slots 758, 759. The plate 752 is also formed with a recess at one side to receive plates 761, 762, these plates being secured to the base plate 752, as by screws 763, 65 see Figures 102, 104, 105 and 106. The plates 761, 762, are substantially the same length as the width of the plate 756, and are arranged in abutting relationship to one side of the plates 755, 756. The plates 761, 762, are formed on their confronting surfaces with recesses to permit the flat blanks to be moved in between the

plates and into the guide plate 756, whereby the marginal portion of the blank 614 overlies the margin of the die sections 755 about the central aperture thereof, see Figures 105, 115. The upper plate 762 is provided with blank guides 765, 766. Corresponding guide pieces 767, 768, are mounted upon carriage guides 769, 770, mounted on the bottom of the heater housing, as by screws 771. The guides extend across the space 558 to the heads 677, see Figure 101.

The guide blocks 765, 766, and the rear pair 767, 768, are spaced apart slightly more than the thickness of a blank. The function of the guide blocks is to assure that the blanks 614 are in flat form and in register with the slot or space between the plates 761, 762. While the blanks are held between the blank carriers 612, the blanks are bowed slightly in a direction lengthwise of the conveyor chain. As the side edges of the blanks are moved between the guide blocks, the blanks are thus flattened out. To aid the edge of the blanks entering between the blocks, the leading edges of the blocks are inclined rearwardly, as at 772. There are similar pairs of guide blocks 773 arranged in the passage 558 on the opposite side of the chains 605 to receive the opposite side edge of the blank, see Figures 85, 101. In other words, when the conditioned blank has reached the station T, opposite edges of the blank are positioned between these guide blocks and is accordingly maintained in a substantially flat condition.

As previously stated, the confronting surfaces of the plates 761, 762, are apertured or recessed to form a blank receiving passage, and this passage is arranged in registration with the blank in the carriers 612 and, of course, in registration with the space between the blank guide-blocks just referred to. The confronting surfaces of the outer portions of the recessed areas in the plates 761, 762, are inclined as at 775, and the sides of the recesses are inclined as at 776, whereby the outer end of the recesses form a rectangular funnel into which the adjacent side edge of the blank is moved and which serves to guide the edges of the blank in the recess formed about the opening in the plate 756, whereby the blank is centered in respect to the opening in the die sections 755.

The blank is transferred from the holders 612 by being pushed from between the holders by a bar 777 mounted on a carriage 778 movable upon four rollers 779 operating in grooves 780, see Figures 92, 101, formed in the carriage guide members 769, 770. The carriage is moved to the left, Figure 101, by a cam 781, Figures 84, 85, mounted on the lower end of a shaft 782 journalled vertically in the bosses 783 depending from the bosses 581, see Figure 88. The upper end of this shaft is provided with a gear 784 arranged in mesh with a gear 785 mounted upon the shaft 579. An arm 786 is journalled intermediate its ends on a stud 787 depending from the under side of the housing 557. One end of this arm is provided with a roller 789 engaging the periphery of the cam 781. The opposite end of the arm is connected to one end of a link 790, the opposite end of which is pivotally connected to the carriage 778. The lever 786 is actuated to move the carriage inwardly to push the blank out of the carriers 612 and into the head by a tension spring 791 secured at one end to a stud 792 depending from the lever, and secured at its other end to a stud 793 carried by a bracket 794 secured to the under side of the bracket

556. The carriage is positively returned by the cam 781. It will be understood that the cam 781 is operable to permit actuation of the lever or arm 786 during the dwell period of the blank conveyor and also while the operating parts of the forming and applying head are in position to permit insertion of the blank between the die plate 755 and the guide plate 756. At this time, a carton is positioned below the head and is 10 elevated into the head by the pedestal 523 which is actuated by the mechanism previously described.

A plate 800 is secured to the under side of the plate 752 and is spaced therefrom by spacers 801 of angular formation and arranged at each corner of the plates, and spacers 802 arranged at the corners of the central aperture. The plate 800 is formed with a central aperture 803 commensurate with the aperture in the base plate 752. A carton clamping jaw 804 is slidably mounted on the plate 800 on each side of the aperture 803, the jaws being movable toward and from the axis of the plates and being guided in such movement by gibs 805 screwed to the plate 800, see Figures 105, 114. The jaws 804 are also formed with notches 806 extending inwardly from their inner edges, these notches being comparable with the notches 758, 759, 760, in the die sections 755 and the guide plate 756. The jaws 804 are beveled, as at 807, on their upper inner edges, and the jaws are formed with lips 808 overlying the top edge of the carton when it is positioned in the aperture 803 and within the jaws 804, see Figure 116. The jaws are moved toward and from the axis of the head by levers 810 journalled intermediate their ends on pivots 811. Each jaw is recessed, as at 812, to receive the rounded end of the lever 810. The opposite end of the lever is pivotally connected to one end of a link 813, as by pin 814. The opposite end of the link 813 is pivotally connected to a ring 815 by pin 816, see Figures 111, 112. With this arrangement, when the ring 815 is oscillated, the jaws 804 are moved toward and 45 from the axis of the head.

In order to provide for convenient adjustment of the jaws individually, the pivot 811, on which the arms 810 are journalled, is formed on the upper end of a stud 817 mounted in the plate 800, the stud being formed with an enlarged collar 818 which is clamped against the plate by means of a nut 819. The pivot portion 811 is formed eccentric with the stud and the collar, whereby the pivot point of the arms 810 may be 50 varied by rotating the stud 817 and clamping it in adjusted position by the nut 819.

The ring 815 is rotatably mounted in a recess formed in the under side of the base plate 752, see Figure 105. This plate is formed on its forward side with a slot 820 through which extends an arm 821 secured at its inner end to the ring 815 and pivotally connected at its outer end to a link 822. These links extend toward the column 554, see Figures 86, 87, the inner ends of the links 65 being adjustably secured in a clamp 823 formed at its center with a recess to receive a roller 824 on the end of an arm 825, the opposite end of which is clamped to a shaft 826. This shaft is journalled vertically in the column 554 and is provided at its lower end with an arm 827, see Figures 89, 91. The outer end of the arm is in the form of a gear quadrant arranged in mesh with a similar quadrant 828 secured to the upper end of a sleeve 829 also journalled vertically in the bottom of the column and provided at its 70 75

lower end with an arm 829 having a roller 831 operating in the cam groove 832 of cam 833 mounted on the main cam shaft 24. With this arrangement, the rings 815 are oscillated to effect inward and outward movement of the carton engaging jaws 804.

As the cartons are elevated by the pedestals 523, the jaws 804 are in outermost position, Figure 115. After the top edge of the carton has slightly entered the jaws, they are moved inwardly. This action properly centers the carton top with respect to the aperture in the die plate 755.

When the blank 614 has been properly transferred over the die 755, and the carton is elevated to the position shown in Figure 116, with the jaw lips 808 overhanging the top edge of the carton, but with the top edge of the carton spaced slightly downwardly from the lips, a centrally located square punch 835 is moved downwardly into engagement with the blank, drawing the central portion of the blank downwardly through the aperture in the die plate 755 and causing the peripheral margin of the blank to be folded upwardly. This downward movement of the punch 835 continues until the blank has been drawn a proper distance into the top of the carton. It will be observed that as the blank is drawn into the carton, the top edge of the carton is protected by the overhanging jaw lips 808.

The punch 835 is secured to the lower end of a stem 836 arranged vertically in the head and being provided at its upper end with an eye member 837 adjustable toward and from the stem by a threaded sleeve 838 and secured in adjusted position by the jam nuts 839, see Figure 105. The stem 836 is slidably mounted in a sleeve 840 extending the major portion of the length of the stem and being in turn slidably mounted in an outer sleeve 841. This outer sleeve is provided at its upper end with a bushing 842 pinned to the outer sleeve, as at 843. The lower end of the sleeve 841 is secured to an annular member 844, as by screws 845. A recessed collar 846 is mounted upon the intermediate portion of the sleeve 841 and is restrained from axial movement thereon by adjustable lock collars 847. A spider member 848 is secured to the lower end of the inner sleeve 840, this member being formed with radial notches in which are pivotally mounted outfolding fingers 849 which are operable to fold the upwardly extending marginal portion of the blank outwardly over the jaw lips 808. These fingers 849 are formed in pairs depending from a cross connecting portion 850 which has extending upwardly therefrom a lever portion 851. These lever portions are formed with relatively narrow ends 852 merging into a downwardly inclined cam surface 854. The lever portions 851 are pivotally mounted upon pins 855 in the spider 848. The fingers 849 are normally positioned in slots 856 formed in the punch 835, as shown in Figures 105, 115 and 116.

The upper end of the sleeve 840 is threaded to receive a stop nut 860 which is held in adjusted position by a set screw 861, see Figure 105. A helical compression spring 862 is interposed between the inner sleeve 840 and the outer sleeve 841. The upper end of the spring abuts against the bushing 842, and the lower end against the hub of the spider member 848, which is pinned to the sleeve 840, as at 863. With this arrangement, the inner sleeve 840 and the spider 848 are moved downwardly until the limit nut 860 engages the

upper end of the outer sleeve 841, as shown in Figure 105.

The annular member 844 is formed with a pair of radially extending bosses 865, and a second pair 866. The bosses 866 are formed with projections arranged in sliding engagement with bearing blocks 867 secured to the sides 751 of the head frame, as by screws 868 and dowel pins 869. The member 844 is held in the bearing blocks by gib 870 secured to the blocks 867 by screws 871. Downfolding fingers 872 are secured to the bosses 865, 866, as by screws 873. As the fingers 872 move downwardly, they pass through the slots 758, 759, in the die sections 755, slots 760 in the guide plate 756, and through the slots 806 in the jaws 804. The downfolding fingers are spaced apart so that the outfolding fingers 849 are positioned intermediate the downfolding fingers, see Figure 102.

Referring now to Figures 86, 87, 89, the outer sleeve 841 is reciprocated vertically by a yoke 875 secured to the upper end of a stem 876 arranged for vertical movement in the housing 524. The lower end of this stem is formed with a roller 877 positioned in the groove of the cam 878 mounted on the main cam shaft 24. The ends of the yoke 875 encircle the collar 846.

The inner sleeve 840 is independently actuated by rocker arms 879 pivotally mounted on brackets 880 secured to the top of the housing 524. Like ends of the arms 879 are pivotally connected to the eye members 837 on the upper ends of the stems 836. The opposite ends of the rocker arms are pivotally connected to a yoke 881 by links 882. The yoke is secured to the upper end of a stem 883, the lower end of which is likewise provided with a roller 884 actuated by cam 885, see Figure 89.

The arrangement of cams 833, 878, 885, and the various adjustments of the mechanism, effect the following operation of the forming and applying head mechanism.

Referring to Figures 105 and 115 to 120, when an end closure blank 614 has been fed into the head and positioned on the die sections 755, as shown in Figure 115, the stem 836 is moved downwardly under the influence of cam 835 and simultaneously, the outer sleeve 841 is also moved downwardly under the influence of cam 878, the stem 836 however moving somewhat more rapidly than the outer sleeve 841. As this downward movement takes place, the pad or punch 835 engages the central portion of the blank, drawing it through the die sections 755 and into the upper end of the carton to approximately the position shown in Figure 116.

During the downward movement of the outer sleeve 841, the inner sleeve 840 is also moved downwardly under the influence of the spring 862. The downward movement of the inner sleeve 840 is limited by the engagement of the limit nut 860 with the bearing block 887. The upper portion of the outer sleeve 841 is slidably mounted in this bearing block, and the block is detachably secured to the rear wall 750 of the head by screws 888.

During the first portion of the movement of these members, the carton elevating stool 523 was elevated from the position shown in Figure 115 to the position shown in Figure 116. This elevation of the stool positions the top edge of the carton a short distance below the lip 808 of the jaws 804, as shown in Figure 116. With the punch 835 and the outfolding fingers 849 in this position, the outer sleeve 841 continues its downward

movement causing the cam ring 890 carried in the member 844 to engage the inclined surfaces 854 on the upper portions of the finger levers 851, contracting these portions towards the center of the head and causing the lower portion of the fingers 849 to move outwardly engaging the upstanding peripheral portion 891 of the blank and folding it outwardly over the top edges of the jaws 804, as illustrated in Figure 117.

The jaws 804 are then moved radially outwardly, the outer sleeve 841 continuing its downward movement, moving the downfolding fingers 872 into engagement with the peripheral portion 891 of the blank and folding it downwardly over the top edge of the carton. During this last downward movement of the fingers 872, the punch or pad 835 is also moved downwardly a slight distance, these movements being sufficient to press the now peripheral inverted channel formation of the blank against the top edge of the carton, see Figure 118. With the punch 835 and the fingers 849 and 872 in this position, the jaws 804 are again moved inwardly to press the outfolded portion of the blank snugly against the exterior of the carton, as illustrated in Figure 119.

The punch 835 is then moved upwardly out of the depressed central portion of the top closure. Thereupon, the jaws 804 are moved outwardly, the downfolding fingers 872 and punch and finger 849 are moved upwardly to initial position, as shown in Figure 120. The stools 523 are then lowered, returning the cartons to the rails 32.

Top closure sealing

After the top closures have been applied to the cartons in the manner just described, they are advanced further to the right, Figures 1 and 3, to the pedestals 512, 522. Over each of these pedestals, there is arranged a top closure sealing head. The sealing heads 904 are positioned above the pedestals 512, and similar heads 905 are positioned above the pedestals 522. The heads 904 are located in proximity to the end of the top closure conditioning apparatus, see Figure 125. The heads 904, 905, are of similar construction and consist of a frame structure having a vertical wall 907 apertured at 908 to receive screws 910 by which the heads are secured to a column 911 mounted upon the top of the cam housing 22. The frame structure of the head is formed with forwardly extending sides 912 terminating in a transversely extending web 913 formed with spaced apart apertures 914 in each of which there is arranged a dowel pin 915. These pins are formed with an upper enlarged portion 916 forming a shoulder engaging the upper ends of bosses 917 formed on the web 913.

The central portion of the pins are positioned in the apertures 914, the lower ends of the pins being formed with a reduced portion 919 and provided with screws 920. A plate 921 is positioned on the lower end portions 919 of the pins, the plate being clamped against the under side of the web 913 by the screws 920, see Figure 129. The plate 921 is formed with four radially extending slots 922, in each of which there is pivotally mounted on a pin 923 an arm 924. A jaw carrying plate 925 is secured to the under side of the plate 921 by a plurality of screws 926. This plate is formed with four radially extending slots, in each of which there is mounted a contracting jaw 928.

The outer portion of the jaws 928 is formed

with a transversely extending slot 930, and each of the arms 924 has a tail piece 931 depending into the slots 930. The inner ends of the jaws 928 are of V formation to receive a corner portion of the carton. The arrangement is such that the edges of the V formation of the jaws overlap, see Figure 133, and the overlapping portion of one jaw is formed with a tongue 933, and the overlapping portion of the adjacent jaw is formed with a groove providing spaced apart portions 934 between which the tongue 933 of the other jaw extends.

The under side of the plate 921 is recessed as at 935 to receive heating elements 936, and to receive a plug having a square depending portion 937. This plug is bored centrally to receive a plug or bushing 938. This inner plug and the plate 921 are bored to slidably receive a stem 939 provided at its lower end with a circular pad 940. The square depending portion 937 of the outer plug is adapted to enter the central depressed portion 941 of the top closure, see Figure 131. Normally, the jaws 928 are spaced outwardly from the plug 937, as shown in Figures 130, 131, providing a space 942 to permit the inverted channel formation 943 of the top closure to enter between the sides of the square portion of the plug and of the jaws.

When the carton C has been elevated by the pedestals 512, 522, to position the top closure into the sealing heads, the jaws 928 are moved inwardly, compressing the inverted channel formation of the top closure against the plug 937. The plug and jaws are maintained at a temperature to effect proper sealing of the coating material on the carton and the top closure by the heaters 936.

The jaws 928 are moved inwardly by oscillation of the arms 924 about their pivots 923. This movement is effected by an annular cam formed of two semi-circular sections 945, 946. These cam sections are mounted upon a carrier 947 having a cylindrical depending portion 948. The sections are retained on the portion 948 by a plate 949 secured to the lower end of the portion 948, as by screws 950, with the peripheral margin of the plate engaging the lower edges of the cam sections. The periphery of these sections is formed with an inclined cam surface 951 and an upper cam surface 952 extending at a lesser angle.

The carrier 947 is formed with bosses 953 slidably mounted upon the upper portions 916 of the guide pins 915, see Figure 129. The upper ends of the arms 924 are provided with rollers 954 which are maintained in engagement with the cam surfaces 951, 952, by helical tension springs 955, the ends of which are connected to pins 956 in the upper portion of pairs of arms 924.

When the carrier 947 is moved downwardly, the cam sections 945, 946, move the upper ends of the arms outwardly and the tail piece 931 inwardly, effecting inward movement of the jaws 928 under great pressure. When the carriers 947 are moved upwardly, the upper ends of the arms 924 are moved inwardly by the springs 955 effecting outward movement of the jaws, as will be apparent.

In order to assure inward movement of the upper ends of the arms 924, the carrier 947 is provided with a depending member 957 arranged in juxtaposition to the roller 954 of each of the arms and having an inclined cam surface 958. Upon upward movement of the carrier 947 and the members 957, these cam surfaces 958 effect inward movement of the rollers 954.

The bore in the cam sections 945, 946, is somewhat greater than the diameter of the portion 948, whereby the cam sections have a free floating movement to a limited extent effective to equalize the pressure on the arms 924. The cam sections are limited in outward radial movement by pins 960 depending from the upper portion of the carrier 948 and extending into apertures 961 formed in the cam sections, these apertures being somewhat larger than the diameter of the pins 960 in order to provide for the floating movement referred to, see Figure 126.

The purpose of the pad 940 is to assure that when the top closure has been sealed to the carton, it will move downward from the sealing heads when the pedestals 512, 522, are lowered. The pads 940 are yieldingly urged downwardly by a helical compression spring 964 mounted in a recess 935 formed in a boss 966 in the central portion of the web 913, the spring acting against the upper end of the stem 939.

The carriers 947 are reciprocated vertically by push rods 968 slidably mounted in the top wall of the housing 911 and being slidably mounted at their lower ends in a yoke 969. The lower ends of the rods 968 are threaded to receive bushings 970 and nuts 971. Washers 972 are interposed between the nuts and the bushings and serve to limit upward movement of the rods 968 relative to the yoke 969. The rods are yieldingly urged upwardly by compression springs 973 encircling the rods and acting between washers 974 positioned on the top wall of the yoke and fixed collars 975, see Figure 126.

The yoke 969 is secured to the upper end of a stem 976, the lower end of which is provided with a fork 977 slidably engaging a guide block 978 mounted on the main cam shaft 24. The fork is provided with a roller 979 positioned in a cam groove 980 in a cam 981 also mounted on the shaft 24.

The upper ends of the rods 968 are connected to links 982 which, in turn, are connected to rocker arms 983 pivotally mounted intermediate their ends on pins 984 carried by brackets 985 mounted on the upper ends of the sealing heads. The opposite ends of the rocker arms are connected to adjustable clevises 986 which, in turn, are connected to eye blocks 987 secured to the carriers 947.

As will be apparent, when the forks 977 are moved upwardly by the cams 981, the push rods 968 are urged upwardly by the helical compression springs 973 and through the linkage 982, rocker arms 983, the carriers 947 are moved downwardly, effecting inward compression movement of the jaws 928 applying sealing pressure on the inverted channel formation 943 of the top closure. Semi-circular bracket members 988 are mounted upon the upper ends of the guide pins 915 and carry suitable terminals 990 for the electrical conductors for the heating elements 936. The lower portion of the sealing heads, including the anvil plug 937 and the jaws 928 are maintained at a proper temperature by a thermostat 931 positioned in the plates 921, 925, of each head.

It will be observed, referring to Figures 125 and 128, that there are four sealing heads mounted upon the column 911. In Figure 128, the bottom of the view corresponds to the upper side of the machine shown in Figures 1 and 125. Accordingly, the two heads shown in the bottom portion of Figure 128 are arranged over one of the guide rails 32, while the two heads at the top of Figure 128 are arranged over the guide rail on the rear side of the machine. The

purpose of employing two top closure sealing heads for each procession of cartons is to avoid the possibility of there being any small part or portion of the inverted channel formation of a top closure not being properly and effectively sealed to the carton. We have found in practise that one head effectively seals the top closures, but in view of the fact that this apparatus operates upon cartons formed of fibrous material and the sealing is effective by coating materials applied to the cartons and top closures, and in view of temperature and humidity changes present in a packaging plant, such as a milk dairy, we have provided for the second set of sealing heads.

Referring to Figure 128, the cartons are advanced from left to right. One side of the square anvil plug 937 is relieved, as at 992, to accommodate the extra thickness of paper at the overlapping side wall seam in the carton body. These cartons are initially placed upon the conveyor rails 32 with the side wall seam on the forward side of the carton. In order to assure that the relief 992 will be properly located, the upper cylindrical flange portion of the plug is provided with apertures 994 to receive a pin 995 projecting upwardly from the bottom plate 925. This arrangement permits the plugs 937 to be properly positioned in any of the four heads on the machine.

It will be understood that these sealing heads are not effective to seal the inverted channel formation 990, 991, at one corner portion of the carton due to the fact that the non-sealable material was applied to the top edge of the carton by the apparatus located at the left end of the machine, Figure 1, and previously described.

The general operation of the machine structure described is as follows: Open ended cartons are positioned successively on the ends of the guide rails at the left end of the machine, Figures 1 and 3, at the positions indicated at 192. These cartons are intermittently advanced along the guide rails by the carton advancing mechanism. As each carton is advanced to the station just preceding the pedestals 248, the carton detector mechanism, associated with the strip applying unit, functions to initiate the feeding and shearing of the strip when the cartons are advanced on the pedestals 248 and elevated thereby. When the non-sealable material is thus applied to the corner portions of the cartons, they are returned to the guide rails 32 and advanced below the filling mechanism 540. During this advancement, the carton detector arms 695 are operable to effect reciprocation of the top closure blank feeder 617 which withdraws the lowermost blank from the magazine 615 and deposits it in blank engaging members 612 positioned below the magazine. These blanks are intermittently advanced in a procession in heat exchanging relation to the heating means 633 and heaters 678. The heaters 678 are mounted on the shaft 680 extending transversely of the machine. The shaft 680 extends through a housing 996 mounted on the housing 554 and in which there is slidably mounted for vertical movement a shaft 997 formed in its central portion with a gear rack 998 meshing with a pinion 999 keyed to the shaft 680. The lower end of the shaft 997 is provided with a piston 1000 slidably mounted in a cylinder portion 1001 secured to the housing 996. The piston and shaft are urged downwardly by a compression spring 1002 encircling the shaft and acting between the piston and an intermediate wall por-

tion of the housing, see Figure 89. The inner end of the cylinder portion 1001 is formed with an aperture 1003, the upper portion of which forms a valve seat for a ball check 1004. The cylinder is also formed with a transversely extending aperture 1005 connecting the aperture 1003 with a vertically extending aperture 1006, the upper end of which is connected to a conduit 1007 extending to a solenoid operated valve 1008. This valve is a conventional two-way valve and when energized connects the conduit 1007 to a conduit 1009 connected to the output by hydraulic pump P, shown in Figure 4 as being mounted in the right end of the cam housing 22, the pump being driven by a pulley 1010 mounted on the main cam shaft 24. When the valve 1008 is deenergized, the conduit 1007 is connected to a conduit 1011 discharging into a tank 1012. Accordingly, when the machine is in operation, fluid pressure is applied against the piston 1000, moving it upwardly in the cylinder to the position shown in Figure 89. This effects a counter-clockwise rotation of the pinion 999 and shaft 680, moving the heaters 678 downwardly into horizontal position, as shown in Figure 93, positioning the heating means 683 in heat exchanging relation to the blanks 614 as they are advanced by the blank conveyor mechanism described. Any fluid leaking or passing by the piston 1000 is discharged from the annular groove 1013 to the tank 1012 through the conduit 1014.

In the event the circuit to the driving motor 28 is interrupted and the machine stopped, the circuit to the solenoid valve 1008 is interrupted, connecting the conduit 1007 to the conduit 1011, and thus permitting the fluid to pass out of the cylinder into the tank 1012. This is effected by the compression spring 1002 moving the piston 1000 downwardly. The ball check 1004 is maintained off from the valve seat by an adjustable screw 1015 threaded into the lower end of the cylinder and extending in the passage 1003. The purpose of this arrangement is to restrain the flow of fluid out of the cylinder to obtain a dash pot action to prevent the heaters 678 from swinging upwardly too rapidly. The upper end of the shaft 997 is provided with a stop collar 1016 secured to the shaft, as by nut 1017 and having a depending sleeve portion 1018. A compression spring 1019 is mounted in the sleeve encircling the upper end of the shaft. The purpose of the spring 1019 is to absorb any jar at the end of the downward stroke of the shaft. The conduits 1007, 1014, extend upwardly from the base of the machine through the columns 559, see Figure 85. The inlet side of the pump P is connected to the tank 1012 by conduit 1020. With this arrangement, over-conditioning of the blanks 614 is prevented in the event the machine is stopped.

When the cartons have been advanced to the pedestals 523, the conditioned blanks 614 have arrived at the transfer position T where they are transferred into the forming and applying heads 677 by which they are formed and applied to the tops of the cartons, as shown in Figure 140. When the cartons are advanced to the pedestals 512, 522, they are elevated into the top closure sealing heads and sealed to the tops of the cartons. Thereafter, the cartons are advanced to the ends of the guide rails 32 to which there is connected any suitable accumulating table or conveyor not shown.

Referring now to the wiring diagram Figure 136, the machine is started by closing a starting switch 1025 which completes a circuit to the coil

of relay 661 from the hot side 117 of the control circuit through the switch 660, wire 1026, contacts of the starting switch 1025, wire 1027, through the normally closed contacts of the stopping switch 1028, wire 1029, relay coil 661, wire 1030, to the common side 118 of the control circuit. Relay 661 furnishes a circuit to relay 1031 through wires 1032, 1033, to relay coil 1031, wire 1034, contact 1035 of relay 661, contact 1036, wires 1030, 1032, to the common side 118. Relay 661 also includes a stick circuit through wire 1039, contacts 1040, 1041, wire 1042, to wire 120, this circuit being shunted around the starting switch 1025 and holding in relay 661.

Relay 1031 furnishes a circuit to the operating coil of the motor starter 662. One side of this coil is connected to the conductor 1032 which extends from the hot side of the control circuit. The opposite side of the coil is connected to the common return 118, through wire 1044, contacts 1045, 1046, wire 1038. The relay 1031 is held in through the contacts 1035, 1036, of relay 661, and also through contacts 1047, 1048, of a switch 1049, the contacts of which are normally closed and are periodically opened by a cam 1050 mounted on the main cam shaft 24, this circuit including wire 1051 connected to wire 1034, the contacts 1041, 1048, wire 1052, the lower contacts 1053, 1054, of relay 1031, and wire 1038.

Energization of the coil 662 closes the main contacts 1055 of the motor starter and opens contacts 119 thereof.

The machine is stopped by opening the contacts of the stopping switch 1028 which breaks the stick circuit to relay 661 and by the opening of the contacts 1035, 1036, of that relay, one of the stick circuits to the relay 1031 is opened. However, relay 1031 will not open until contacts 1047, 1048, are opened by the cam 1050. This cam is so positioned on cam shaft 24 to open the contacts 1047, 1048, only when the pedestals are in the lowered position, or when there are no carton tops in the sealing heads. Due to the fact that these heads are heated, it would be injurious to the carton closures if they were left in the heated heads for an indefinite period of time. When the relay 1031 opens, the circuit to the motor starter 662 is opened, stopping the driving motor 28. The starting motor 662 may be intermittently closed by a jogging switch 1058 operable when closed to connect wire 1038 to wire 1045.

It will be observed that the hot side 117 of the control circuit is energized by the switch 123 associated with the carton conveyor elevating mechanism. When the contacts of this switch are opened in the manner previously explained during the vertical adjustment of the rails 32, all power to the actuating mechanisms is shut off. The top closure blank gauging switch 660 is also connected in the circuit to the relay 661. Accordingly, when this switch is opened, because two or more blanks 614 have been removed from the magazine at one operation of the blank feeder, the relay 661 is opened whereupon relay 1031 opens, breaking the circuit to the motor starter 662, causing the machine to stop. The solenoid operated valve 1008 is connected to wire 1032, through wire 1061, and to wire 1052 by wire 1061, whereupon when the contacts 1053, 1054, of relay 1031 open, the valve is deenergized, permitting the heaters 678 to move out of heat exchanging relation with any blanks positioned on the blank conveyor.

The machine structure described is operable

to rapidly advance light cartons formed of fibrous material and apply and seal top closures to the open ends of the cartons. It will be apparent that particular attention has been given to the constructions and arrangements whereby the machine is particularly compact, and the mechanisms particularly durable and reliable in operation with a high output of cartons.

The top closure blanks 614 are coated, at least on their under sides, with a material which, at elevated temperatures, becomes adhesive and is effective to seal the top closures to the tops of the cartons. The purpose of the application of the seal baffle at one corner portion of the carton is to prevent the contiguous portion of the top closure from sealing permanently to the carton. This portion is defined by a score line 1070, and forms a portion which can be conveniently moved upwardly from the carton to provide an opening at the corner of the carton through which the contents thereof can be poured.

What we claim is:

1. Apparatus for handling cartons, a guide rail, carton advancing mechanism operable to intermittently advance a procession of cartons along said rail to and past mechanism for applying non-sealable material to a corner portion of the top edge of each carton, said mechanism comprising means for supporting a supply of non-sealable strip material, strip feed means operable to feed the leading end portion of said strip into juxtaposition to one corner of the top portion of each carton as the same is presented to said mechanism, jaw members movable into engagement with the inner and outer surfaces of said corner portion of the carton, a strip clamp operable to clamp the leading portion of the strip against the outer surface of the carton, a cutter operable to sever said leading portion of the strip above the top edge of the carton, a folding member operable to fold that portion of the severed strip extending about the top edge of the carton laterally over the top edge of the carton, a downfolding member operable to fold the lateral portion downwardly against the inner surface of the carton, and motion transmitting means operable for actuating said members in timed relation.

2. Apparatus for closing cartons comprising a guide rail adapted to support a procession of open-ended cartons, a seal baffle applying station and an end closure applying station located in spaced relation along said guide rail, means at said seal baffle applying station for supporting a supply of non-sealable strip material, feeding means operable to feed the free end of said strip in juxtaposition to a corner portion of the top edge of each carton presented at said seal baffle applying station, cutting means operable to sever said portion from the strip, and folding means operable to fold said severed piece over the top edge of the carton, means cooperable in the absence of a carton in said procession to render said strip feeding and severing means inoperable, carton advancing means operable to advance said procession and successively present cartons at said stations, and means at said end closure applying station operable to apply end closures to each carton presented at said station.

3. Apparatus for processing cartons comprising an elongated guide rail, carton advancing means operable to advance a procession of cartons along said rail to and past mechanism for applying non-sealable material to a portion of the top edge of the cartons, said mechanism

comprising means for supporting a supply of non-sealable strip material, strip feed means operable to feed the leading end portion of said strip into juxtaposition to one corner of the top portion of each carton presented at said mechanism, strip forming means operable to form the leading portion of the strip into V formation, a strip clamp operable to clamp said leading portion of the strip against the outer surface of the carton with the apex of said portion in register with the corner of the carton, a cutter operable to sever said leading portion of the strip above the top edge of the carton, folding means operable to fold the upwardly extending part of the severed portion laterally over the top edge of the carton and to form a tuck in said portion at the corner of the carton, downfolding means operable to fold the lateral portion downwardly and iron the same against the inner surface of the carton, and motion transmitting means operable to actuate said members in timed relation.

4. Apparatus for processing cartons comprising an elongated guide rail, carton advancing means operable to advance a procession of cartons along said rail to and past mechanism for applying non-sealable material to the top portion of the cartons, said mechanism comprising means for supporting a supply of non-sealable strip material, strip feed means operable to feed the leading end portion of said strip in juxtaposition to one corner of the top portion of each carton presented at said mechanism, strip forming means operable to form said leading portion of the strip against the outer surface of the carton, with the apex of said portion in register with the corner of the carton top, a cutter operable to sever said leading portion above the top edge of the carton, a folding member operable to fold that portion of the severed strip extending above the top edge of the carton laterally over said top edge, downfolding means operable to fold the lateral portion downwardly and iron the same against the inner surface of the carton, and motion transmitting means operable to actuate said members in timed relation.

5. Apparatus for closing open ended cartons comprising a guide rail adapted to support a procession of cartons, a seal baffle applying station and a top closure applying station located along said rail in spaced relation, carton advancing mechanism operable to present cartons of said procession successively to said stations, mechanism at said seal baffle applying station operable to clamp a piece of non-sealable sheet material against a corner portion of the top of each carton presented at said station with a portion of said sheet extending upwardly from the top edge of the carton, folding means operable to form a tuck in said upwardly extending portion of the sheet at the corner of the carton and to fold said portion over the top edge of the carton and downwardly on the inner surface thereof, and mechanism at said end closure applying station to apply an end closure to the top of the carton.

6. Mechanism for forming end closures from flat blanks and applying the same to the tops of open ended cartons comprising a die member positioned above the carton and in registration therewith, carton engaging jaws movable into and out of engagement with the sides of the cartons, means cooperable to move said jaws into engagement with the sides of the carton, a plunger movable through said die and being cooperable therewith to press the central portion

of the blank into the top of the carton with the marginal portion of the blank extending upwardly from the top edge of the carton, out-folding members movable outwardly into engagement with said upstanding portion of the blank and fold the same outwardly over said jaws, downfolding members operable to fold said outwardly extending portion downwardly, and means cooperable to move said jaws outwardly from the carton during such downfolding, and to move said jaws inwardly to press said down-folded portion against the carton walls, and means operable to move said plunger upwardly and said jaws outwardly to release the carton.

7. Apparatus for sealing end closures having an inverted peripheral channel to the tops of cartons rectangular in cross section comprising a frame, a plate mounted on the frame and having a central aperture adapted to receive the end portion of a carton with a closure thereon, a plug member fixed on the plate and positioned in said aperture to enter the central depressed portion of the closure, a series of jaws slidably mounted in said plate and being movable toward and from the axis of the carton, each of said jaws being formed on its face with a V-shaped notch adapted to engage a corner portion of the top closure, jaw actuating members pivotally mounted in said frame in proximity to the plate and extending upwardly therefrom, a carrier mounted on the body for movement toward and from said plate, a cam member mounted on said carrier and being movable into engagement with said actuating members to effect inward movement of said jaws simultaneously to compress said peripheral channel of the top closure against said plug, said cam being mounted on said carrier for radial movement relative to the carrier, and heating means operable to maintain said jaws at elevated temperature.

8. Apparatus for closing cartons comprising a frame, a guide rail adapted to support a procession of cartons, a carton detecting station and an end closure applying station spaced along said rail, an end closure applying mechanism at said end closure applying station and operable to apply end closures to cartons presented at said station, carton advancing means operable to intermittently advance a procession of cartons along said guide rail, a member positioned in proximity to said guide rail, means cooperable upon movement of said member to render said end closure applying means inoperable, a carton detector movably mounted on the guide rail at said carton detecting station, said carton detector having a latch portion normally positioned in latching engagement with said member to restrain the same from movement, means operable as each carton of said procession is presented at said carton detecting station to urge said latch portion out of latching position, and said detector having a carton engaging portion adapted to engage a carton presented at said station and prevent movement of said latching portion out of latching engagement with said member.

9. Apparatus for closing cartons comprising a frame, a guide rail adapted to support a procession of cartons, means operable to adjust said rail vertically to different selected positions, a carton detecting station and a carton closing station spaced along said rail, mechanism at said carton closing station operable to apply end closures to cartons presented at said station, carton advancing means operable to intermittently ad-

vance a procession of open-ended cartons along the guide rail, a member positioned in proximity to said rail, means cooperable upon movement of said member to render said end closure applying mechanism inoperable, a carton detector movably mounted on the guide rail at said carton detecting station, said detector having a latch portion normally positioned in latching engagement with said member at any selected position of said guide rail to restrain said member from movement, means operable as each carton of said procession is presented at said carton detecting station to urge said latch portion out of latching position, and said detector having a carton engaging portion adapted to engage a carton present at said station and prevent movement of said latching portion out of latching engagement with said member.

10. Apparatus for closing cartons comprising a frame, a guide rail adapted to support a procession of cartons, a carton detecting station and an end closure applying station spaced along said rail, end closure applying mechanism at said end closure applying station and operable to apply end closures to cartons presented at said station, carton advancing means operable to intermittently advance a procession of cartons along said guide rail, a member positioned in proximity to said guide rail, means cooperable upon movement of said member to render said end closure applying means inoperable, a carton detector movably mounted on the guide rail at said carton detecting station and having a latch portion normally positioned in latching engagement with said member to restrain the same from movement, means yieldingly urging said detector out of latching engagement, a cam mounted in the guide rail and normally engaging said detector and maintaining the same in latching engagement, means operable as each carton of said procession is presented at said carton detecting station to move said cam out of engagement with said detector and permit said latch portion to move out of latching position, said detector having a carton engaging portion adapted to engage a carton present at said station and prevent movement of said latching portion out of latching engagement with said member.

11. Apparatus for closing cartons comprising a frame, a guide rail adapted to support a procession of cartons, means operable to adjust said guide rail vertically to different selected positions, a carton detecting station and a carton processing station spaced along said rail, carton processing mechanism at said carton processing station and operable to process cartons presented at said station, carton advancing means operable to intermittently advance a procession of open ended cartons along said guide rail, a shaft journalled vertically in the frame, means cooperable upon rotation of said shaft to render said carton processing means inoperable, a carton detector member movably mounted on the guide rail at said carton detecting station, said member having a latch portion normally positioned in latching engagement with said shaft at any selected position of said guide rail to restrain said shaft from rotation, means operable as each carton of said procession is presented at said carton detecting station to urge said latch portion out of latching position, and said detecting member having a carton engaging portion adapted to engage a carton present at said station and prevent movement of said latching portion out of latching engagement with the shaft.

12. Apparatus for closing cartons comprising a frame, a guide rail adapted to support a procession of cartons, a carton detecting station and an end closure applying station spaced along said rail, end closure applying mechanism at said end closure applying station, means for supporting a supply of end closure blanks, end closure blank feeding means operable to successively remove blanks from said supply and feed the same to said applying mechanism, carton advancing means operable to intermittently advance a procession of open-ended cartons along said guide rail, a shaft journalled vertically in the frame, means cooperable upon rotation of said shaft to render said blank feeding means inoperable, a carton detector member movably mounted on the guide rail at said carton detecting station, said member having a latch portion normally positioned in latching engagement with said shaft to restrain the same from rotation, means operable as each carton of said procession is presented at said carton detecting station to urge said latch portion out of latching position, and said detector member having a carton engaging portion adapted to engage a carton present at said station and prevent movement of said latching portion out of latching engagement with said shaft.

13. Apparatus for closing cartons comprising a frame, a guide rail adapted to support a procession of cartons, a carton detecting station and an end closure applying station spaced along said rail, end closure applying mechanism at said end closure applying station and operable to apply end closures to the cartons successively presented at said station, carton advancing means operable to intermittently advance a procession of cartons along said guide rail, a shaft journalled vertically in the frame, and means cooperable upon rotation of said shaft to render said end closure applying mechanism inoperable, a carton detector member movably mounted on the guide rail at said carton detecting station, said member having a latch portion normally positioned in latching engagement with said shaft to restrain the same from rotation, a push rod slidably mounted in said guide rail, means operable to effect actuation of said push rod, and means operable upon such actuation to urge said latch portion out of latching position, and said detector member having a carton engaging portion adapted to engage a carton present at said station during such actuation, and prevent movement of said latching portion out of latching engagement with said shaft.

14. Apparatus for closing cartons comprising a frame, a guide rail adapted to support a procession of cartons, a seal baffle applying station, an end closure applying station spaced along said rail, a carton detecting station associated with each of said applying stations, mechanism at said seal baffle applying station operable to apply a seal baffle to a portion of the top edge of each carton presented at said station, end closure applying mechanism located at said end closure applying station and operable to apply an end closure to each carton presented at said station, carton advancing means operable to intermittently advance a procession of open-ended cartons along said guide rail, a control shaft associated with each of said applying mechanisms, means cooperable upon rotation of said shafts to render said applying mechanisms respectively inoperable, a carton detector member movably mounted on the guide rail at each

5 of said detecting stations, each of said members having a latch portion normally positioned in latching engagement with said shafts respectively to restrain the same from rotation, means operable as each carton of said procession is presented at said carton detecting stations to urge said latch portions out of latching position, and each of said detector members having a carton engaging portion adapted to engage a carton present at said stations, and prevent movement of said latching portions out of engagement with said shafts.

said jaws into engagement with the outer wall of said inverted channel, and said cam having free radial movement relative to said carrier.

18. Apparatus for sealing end closures having an inverted peripheral channel to the tops of cartons rectangular in cross section comprising a body, a plug member carried by the body and adapted to enter the central depressed portion of the closure, a series of sealing jaws mounted in the body for movement radially of the axis of the plug, a carrier slidably mounted on the body toward and from said plug, a cam mounted on the carrier, a jaw actuating member connected to each of said jaws, said cam being operable upon movement of the carrier toward said plug to engage all of said actuating members simultaneously, said actuating members being operable upon engagement by the cam to move said jaws into engagement with the outer wall of the inverted channel, and said cam being mounted for free radial movement relative to the carrier.

19. Apparatus for forming flat end closure blanks coated with adhesive into closures with inverted peripheral channels and sealing said channels to the top edge of cartons rectangular in cross section comprising a die plate positioned above the carton and being formed with a rectangular shaped aperture arranged in registration with the top edge of the carton, a plunger mounted for movement axially of the carton through said aperture and being operable upon such movement to draw a blank positioned on the die plate through said aperture into the open end of the carton with the marginal portion of the blank upstanding, a first series of lateral folding fingers normally positioned within the periphery of the plunger means operable to move said fingers outwardly to fold said upstanding portion laterally over the edge of the carton, a second series of fingers surrounding said plunger and being movable vertically independently of the plunger to fold said lateral portion downwardly about the sides of the carton, and a series of jaws arranged below said die plate and operable to compress the folded portion of the blank against the carton.

20. Apparatus for forming flat end closure blanks coated with adhesive into closures having inverted peripheral channels and sealing said channels to the top edge of cartons rectangular in cross section comprising a body, a die plate carried by the body and being formed with a rectangular aperture arranged in registration with the open end of the carton, a plunger slidably mounted in the body for movement through said aperture and being operable upon such movement to draw a blank positioned on the die plate through the aperture and into the open end of the carton with the marginal portion of the blank upstanding, a first series of lateral folding fingers surrounding said plunger and being normally positioned within the periphery thereof, means operable to move said fingers outwardly to fold the upstanding portion of the blank laterally over the edge of the carton, a second series of down folding fingers mounted in the body for vertical movement relative to the plunger, means operable to move said second fingers downwardly to engage said lateral portion of the blank and fold the same downwardly about the sides of the carton, a series of jaws slidably mounted in the body for movement toward and from the axis of the carton and being operable to compress said down folding portion of the blank

75

24. Apparatus as defined in claim 19 wherein

against the carton, and said second series of fingers being operable to maintain said down folded portion of the blank in down folded position until the same is engaged by said jaws.

21. Apparatus for forming flat end closure blanks coated with adhesive into end closures having inverted peripheral channels and sealing said channels to the top edge of cartons rectangular in cross section comprising a body, a die plate carried by the body and formed with a rectangular shaped aperture arranged in registration with the open end of the carton, a series of jaws slidably mounted in the body for movement toward and from the side walls of the carton and being formed with lips adapted to overlie the top edge of the carton, a plunger slidably mounted in the body for movement through said aperture and being operable upon such movement to draw a blank positioned on the die plate through the aperture into the open end of the carton with the marginal portion of the blank upstanding, a series of folding fingers operable to first fold the upstanding portion of the blank laterally over the top edge of the carton and to subsequently fold said lateral portion downwardly about the side of the carton, actuating means operable to move said jaws inwardly with the lip portions overhanging the top edge of the carton during said drawing and lateral folding operations, and to move said jaws outwardly from the carton during said down folding operation, and to subsequently move said jaws inwardly against said down folded portion and press the same under pressure against the carton.

22. Apparatus for forming flat blanks coated with adhesive into end closures having inverted peripheral channels and sealing said channels to the top edge of cartons rectangular in cross section comprising a body, a die plate carried by the body and formed with a rectangular shaped aperture arranged in registration with the open end of the carton, a series of jaws arranged below the plate and engaging the sides of the carton, each jaw having a lip portion overlying the top edge of the carton, a plunger movable through said aperture and being operable upon such movement to draw a flat blank positioned on the die plate into the open end of the carton with the marginal portion of the blank upstanding, a series of outfolding fingers normally positioned within the periphery of the plunger and being movable radially outwardly therefrom and being operable upon such movement to fold the upstanding portion of the blank laterally over said jaw lips, jaw actuating means operable upon completion of said outfolding movement of said fingers to move said jaws outwardly from the carton, a series of down folding fingers surrounding said plunger and mounted for vertical movement relative thereto, means operable to move said down folding fingers downwardly and said latter fingers being operable upon such downward movement to fold the lateral extending portion of the blank downwardly about the top of the carton, said jaw actuating means being operable to effect inward movement of said jaws against the down folded portion of the closure to apply sealing pressure thereto and thereafter effect outward movement of the jaws, and means operable to move said plunger and fingers upwardly from the carton.

23. Apparatus of the type defined in claim 16 wherein there is provided means operable to render the strip applying mechanism inoperable when no carton is presented at said station.

the surfaces of the jaws confronting the carton have recesses to receive said second series of downfolding fingers.

25. Apparatus for forming flat end closure blanks coated with adhesive material with inverted peripheral channels and sealing said channels to the top edge of cartons rectangular in cross section comprising a body, a die plate carried by the body and positioned above the carton, said die plate being formed with a rectangular aperture arranged in registration with the top of the carton, a plunger slidably mounted in the body for movement through said aperture and being operable upon such movement to draw a blank positioned on the die plate into the open end of the carton with the marginal portion of the blank upstanding, a series of folding fingers surrounding said plunger, actuating mechanism operable to move said fingers outwardly from the plunger to fold the marginal portion of the blank over the top edge of the carton and thence downwardly to fold said marginal portion about the side walls of the carton, a series of jaws arranged below said die plate and movable into engagement with the folded portion of the blank to compress the same against the carton, the surfaces of said jaws confronting the carton being formed with slots to receive said downfolding fingers.
